ROTARY BUNDLE BINDING AND TYING
MACHINE

James Marshall Leaver, Jr., Oakland, Calif.

Application May 10, 1920, Serial No. 380,375

186 Claims. (Cl. 100—31)

This invention relates to machines for binding bundles, boxes, or like, and more particularly to machines for wrapping and securing a taut binder in band formation about a bundle, without drawing the binder across any edge or face of the bundle.

An object of the invention is to provide a machine which is readily adaptable for all conditions of service.

10 Another object of the invention is to provide a machine which will place one or more bands at any desired point about a bundle and secure the same in place.

Another object of the invention is to provide a 15 machine which is capable of binding a plurality of bundles at one time.

Another object of the invention is to furnish a machine which will tension and put a band under predetermined tension about bundles or 20 the like.

Another object of the invention is to provide means which, when wire is used, will so flex the wire as to cause it to lie flat against and tightly hug the sides of a bundle when applied thereto 25 and secured in band formation thereabout.

A further object of the invention is to provide a bundle binding machine which, when wire is used will either coil or intertwist the terminals of the binder with only minor changes in its 30 parts.

Another object of the invention is to provide bundle clamping means which will effect quick and firm clamping and holding of bundles to be bound, irrespective of the size of the bundles 35 within the range of movement of the bundle clamp, without the necessity of adjustment of the clamping means.

Another object of the invention is to provide bundle abutment means adjustable relative to 40 the bundle support, whereby bundles of varying widths may be properly located in binding position with respect to the binder securing means.

Other objects of the invention will be apparent and understood from a consideration of the 45 following detailed description taken in connection with the accompanying drawings forming part of this specification, with the understanding, however, that the invention disclosed herein embodies new and useful features which are not 50 confined in any strict conformity with the showing of the form of machine in the drawings, but may be modified and adapted to other forms of bundle binding machines.

In order that the principles of the invention 55 may be best understood, I have herein disclosed

for illustrative purposes, in the accompanying drawings, embodiment of such invention in a form of machine adapted for binding incompressible objects, or units, such as a box, or a bundle consisting of a series of boards, box 5 shocks, or the like, with a tensioned wire, and securing the wire into band formation thereabout while the wire is under tension, thereby insuring a compact and firmly bound bundle when non-expansible, or inelastic objects or material is 10 bound, it being understood that certain features of the invention may be used and incorporated to advantage in other and widely differing forms, or types, of binding machines, than that herein selected for illustration, such as machines for 15 binding either compressible or incompressible bundles, packages, or the like, with wire, a flat band, rope, cord, or the like.

It will be understood by those skilled in the art, that of the various binding elements employed 20 for binding bundles, packages, and the like, the use of wire has presented the most difficult problem, due to the difficulty in effecting tight hugging of the wire against the sides and periphery of the bundle, and therefore, in selecting the 25 present form of machine for illustrative purposes, I have done so in order to describe and make clearly apparent the manner in which my invention, through flexing of the wire, overcomes such difficulty and effects tight hugging of the 30 wire against the sides and periphery of the bundle.

In the drawings—

Figure 1 is a front elevation of a machine constituting an embodiment of the invention. 35

Fig. 2 is a similar view of a portion of the machine shown on an enlarged scale.

Fig. 3 is a plan view of a portion of the machine shown in Fig. 1, but shown on a larger 40 scale.

Fig. 3a is a similar view of the remainder of the machine.

Fig. 4 is a vertical section on the line 4—4 of Fig. 1 showing the manner in which the bundle 45 clamp elevating cam raises the clamp or jaw against the pressure of the clamp actuating means.

Fig. 4a is a view similar to Fig. 4, but with a wire convexing and slack compensating means 50 associated with the end bundle holding frame.

Fig. 5 is a vertical section on the line 5—5 of Fig. 1.

Fig. 5a is a view similar to Fig. 5, but with a wire convexing and slack compensating means 55

associated with the intermediate bundle holding frame.

Fig. 6 is a vertical section on the line 6—6 of Fig. 1 showing the manner in which the clamp elevating cam has raised the bundle clamp or jaw to bundle receiving or bundle discharging position against the pressure of the clamp actuating means.

Fig. 7 is a vertical section on the line 7—7 of Fig. 1 showing an assembly of bundle binding and tying mechanisms and operative features thereof in the form of a complete binding and tying unit mounted on a single standard and adapted to receive bundles advanced in lengthwise direction, directly into binding position.

Fig. 8 is an elevation of one of the end bundle holding frames viewed from the outer face thereof.

Fig. 9 is an elevation of one of the intermediate or open-mouthed bundle holding frames showing the movable clamp or jaw in bundle holding or clamping position under the pressure exerted by the springs which actuate the bundle clamp or jaw.

Fig. 10 is a fragmentary elevation of the end bundle holding frame shown in Fig. 8, looking from the other side thereof, illustrating the lower position of the roller, which rides on the elevating edge of the clamp lifting cam, when the movable clamp or jaw is in clamping position.

Fig. 11 is a sectional view on the line 11—11 of Fig. 10 showing the clamp or jaw forced into bundle holding and clamping position by power of the pressure spring which actuates the clamp and provides adaptability to compensate for the clamping of bundles of different sizes within the limits of yieldability of said power exerting spring.

Fig. 12 is a sectional view on the line 12—12 of Fig. 11 showing construction whereby the bundle clamp or jaw is slidably mounted relative to the bundle holding structure.

Fig. 13 is a top plan view with parts in section of one of the intermediate bundle holding frames.

Fig. 14 is a sectional view on the line 14—14 of Fig. 13 showing construction whereby the bundle clamping means or jaws are slidably mounted relative to the bundle holding structure and also showing the power actuating springs, which effect the clamping and holding of the bundle, and which springs are adapted to compensate for the clamping of bundles of different sizes, within the limits of yieldability of said power exerting means.

Fig. 15 is a detail sectional view of the clutch mechanism showing the parts thereof in disengaged position.

Fig. 16 is a similar view showing the parts in engaged or driving position.

Fig. 27 is an elevation of a wire coiling cam.

Fig. 28 is a detail showing the top of the knotter head for coiling, and also illustrating the strike roller with which the cutter blade engages.

Fig. 29 is a similar view showing the cutter in 10 the position it assumes when severing the band.

Fig. 30 is a view similar to Fig. 28 but illustrating a twisting knotter head and omitting the cutter blade.

Fig. 31 is a longitudinal sectional view of one 15 of the intermediate standards with the associated tensioning device.

Fig. 32 is a perspective view of a portion of a tension arm showing a wire guide.

Fig. 33 is a detail view showing a portion of a 20 bundle with a coil formed at a corner.

Fig. 34 is a similar view showing a twist at the corner.

Fig. 35 is a front elevation showing the manner in which the intermediate binding and tying units 25 may be arranged on the base of the machine to effect the binding and tying of bundles without the employment of the end binding and tying units.

Figs. 36, 37, 38, and 39 are diagrammatic views 30 illustrating various positions of a bundle as it is rotated and a taut wire is applied and secured into band formation thereabout, and also the oscillatory movement of the binder wrapping and tensioning device which so tensions and directly 35 applies the wire, flexed, thereabout, as to cause the wire to tightly hug and lie flat against the entire periphery of the bundle, the tension and stress inherent in the wire by reason of such flexing, tending to cause the wire to press convex inwardly toward and against the sides of the bundle. 40

In the present instance, the particular machine herein is constructed to draw wire from a coil, and to flex and so wrap the wire under sufficient 45 tension around a bundle, box, or the like, as to cause it to tightly hug the sides of the bundle, without dragging it over any corner or edge thereof, and to tie the wire without overstraining it or causing injury to the tie. Means are provided 50 for flexing and tensioning the wire for wrapping about the bundle. Means are also provided for maintaining the wire taut by preventing slack therein during the operation of the wrapping of the wire into band formation about the bundle. 55

The machine is provided with a bundle support having a knotter or wire twisting device disposed in fixed position below the plane of the support, and in the plane of wrapping of the wire about the bundle, for receiving and uniting the wire 60 wrapped about the bundle. Means adjustable toward and from the twisting device are provided for locating bundles of differing widths in proper binding and tying position on the support. Means are also provided for quickly, firmly and compensatingly clamping the bundles so located, and bundles of varying dimensions within the range of movement of the clamp without injury to the bundles or the machine. The wire is gripped and in tension when the twisting device is operated to 65 tie the wire encircling the bundle in band formation thereabout. Means are provided for cutting the wire then extending from the tie to the supply. Means are also provided for timing the operation of the means for effecting wrapping of 70

the wire about the bundle and for timing the operation of the twisting means, the cutters and the grippers. Means are also provided for releasing the bundle clamping means from the bundle upon completion of the binding and tying of the band about the bundle.

The machine is provided with means for placing one or more bands at any desired point, or points, about a bundle, or a plurality of bundles, 10 and to secure the same in place thereabout in each cycle of binding operation.

The machine also embodies other features of construction and operation which will become apparent as the specification proceeds.

15 Referring to Fig. 1, the base 40 of the machine is shown mounted on the castors 41. A standard 42 is fixed near one end of the base and carries a rotary member or rotary frame, with associated parts. A similar standard 43 is mounted 20 on the base so as to be adjustable toward and from the fixed standard 42 and carries parts corresponding to those supported by the fixed standard.

At the end of the base upon which the fixed 25 standard 42 is secured, a motor 44 is placed, having a driving pinion 45. This pinion meshes with a gear 46 secured upon a stub shaft 47 rotatable in suitable bearings fixed to the base of the machine. A gear 48 is mounted upon the shaft 47 30 so as to turn independently thereof. The gears 46 and 48 are secured respectively to the driving and driven parts of a clutch to be presently described. A pinion 49 meshes with gear 48 and is mounted upon a stub shaft 50 which also carries 35 a gear 51. Meshing with the latter is a pinion 52 keyed upon the main drive shaft 53 extending the length of the machine.

Mounted upon the drive shaft 53 and near the pinion 52 is a gear 54 which is meshed with an 40 idler gear 55, in turn meshed with a large gear 57 which rotates end member 61 by means of the collar 59 rotatable in the upper end of standard 42. The drive shaft 53 has a key-way or spline 53a, shown in Figs. 3 and 3a, with which a gear 45 54a is engaged so that said gear is movable along said shaft and rotatable therewith. The gear 54a is secured relatively to the standard 43 so that when the latter is adjusted along the base toward and from the fixed standard 42 the gear 54a will 50 move therewith. An idler 55a engages with the gear 54a and also with the large gear 56 similar to gear 57. The large gear 56 is made fast to the collar 58 in turn secured to the end rotary member 60. When the standard 43 is adjusted it 55 carries with it the rotary member 60, and associated parts, while the gearing 54a, 55a, and 56 is also driven by the driving shaft 53 regardless of the position of the standard 43.

For controlling the cycle of operation of the 60 machine an operating lever 62, (Figs. 2, 3, and 5) preferably provided with a foot pedal, as shown, is secured to a rock shaft 63 running the length of the machine. While but one of these operating levers 62 has been shown, it is obvious that 65 more than one might be employed to provide operating control of the machine from different points. The clutch mechanism, and operating parts thereof, shown in Figs. 15 to 20, inclusive, will now be described. A sleeve 64 is secured to 70 that end of the rock shaft 63 near the motor. A bracket 65 is mounted upon the machine base 40 below the clutch for the purpose of supporting parts to be described. An arm 66 is made fast to the shaft 63 by means of the sleeve 64 and is provided at its outer end with an elongated slot 67

(see Figs. 17 and 20, inclusive). The slot 67 receives a pin 68 which also is passed through a slot 70 provided at the lower end of a vertically slideable arm 69. The latter arm is slideable in a frame 71 supported by the bracket 65. Within the frame 71 a pair of guide rods 72 are fixed, which rods run parallel with the movable arm 69 and which have coil springs 73 mounted thereon. The upper end of the arm 69 has a jaw 74 urged upwardly by the springs 73. 10

The function of the jaw 74 is to engage with a clutch pin 79 (Fig. 15) slidably mounted within the clutch body 77 and pressed outwardly by a spring 80 whose tension is regulatable by a screw plug 80a. The clutch body is provided with a 15 peripheral groove 78 intermediate its ends and the clutch pin 79 has a slot 81 which registers with the groove 78 when the pin is contained within the clutch body. When the clutch pin is released it projects from the clutch body and engages with one of the notches 76 in the clutch face plate 75, as shown in Fig. 16. The latter element is secured to the gear 46 while the clutch body 77 is secured to the gear 48. As seen in Fig. 20 the pin-engaging end of the jaw 74 is cut 20 away to provide a cam face 82. 25

The operation of the clutch is as follows: Foot pressure on the lever 62 is transmitted by means of the shaft 63 to the arm 66. Assuming that the parts are in the position illustrated in Figs. 15 and 17, such movement of the arm 66 will, after said arm has swung through a certain arc, pull the jaw 74 downwardly against the resistance of the springs 73. This will permit the pin 79 to move outwardly from the clutch body, as illustrated in Fig. 16, and engage with one of the notches 76. Then the clutch face plate 75, which is united with the constantly rotating gear 46 will cause rotation of the clutch body 77 and consequently of the gear 48 and the drive shaft 53. 30 35 40

It will be clear that certain rocking of the shaft 63 and consequently of the arm 66 will take place before the jaw 74 releases the clutch pin. The purpose of this lost motion connection will be made clear later. When the jaw 74 is permitted 45 again to press against the groove 78 of the rotating clutch body its cam face 82 will, when the clutch pin is rotated against the same, cause the latter to move backwardly into the clutch body and out from the notch 76. Thereupon rotation 50 of the drive shaft 53 will cease.

The bundle clamping mechanism of this invention will now be described and the new and useful disclosures and objects of such mechanism will be apparent from such description and the 55 showing of the drawings and appended claims.

It will be understood by those skilled in the art, that the difficulty heretofore existing with respect to mechanical clamping mechanisms of the prior art has been that the slow acting clamps 60 thereof requiring predetermined distance of travel and adjustment for each size of bundle to be bound, have not been adaptable to the general requirements and conditions of service in connection with machines adapted for binding 65 either compressible or non-compressible objects, packages, or the like.

It will be apparent from the following description of my new and useful mechanical clamping mechanism, and the showing of the drawings, that 70 I have overcome such difficulty by construction insuring rapid and firm clamping of objects, packages, bundles, or the like, irrespective of whether the same consist of compressible or incompressible material, and irrespective of the size of the 75

bundle within the distance of travel of the bundle clamp.

Referring to Figs. 4, 5, 6, and 7, it is seen that the wire is so arranged for quick application to the lower face of the bundle, that it is necessary to hug or quickly clamp and hold the bundle in tying location prior to application of the tensioned wire thereto, in order to prevent lifting, or shifting, or dislocation of the bundle when the wire is so applied, and it will be understood by those skilled in the art, that in quick clamping of a bundle upon the initiation of the binding cycle increased capacity in bundle binding machines is assured.

It is well known in the bundling of boards, box shooks, and the like, that some of the units advanced into the machines for binding and tying consist of a series of straight and aligned pieces and therefore are substantially of solid binding form when placed for binding, whereas other units of boards or box shooks—particularly of thin material—including warped, cupped, and twisted pieces which require aligning and compacting into binding form. Therefore, it will be understood that such showing, with respect to said boards or box shooks, is for the purpose of informing those skilled in the art as to the adaptability of the clamping features of the clamping of either compressible or incompressible bundles, or objects, and that the clamp is compensatingly actuated with respect to various sizes of bundles or objects to be bound within the predetermined limits of movement of the clamp.

It will be understood that the mechanisms mounted on either end frame, or standard, conveniently may be duplicates of those provided on the other end frame, or standard. Therefore, a detailed description of one of the mechanisms on one end frame, or standard, will suffice for both. Secured to the shaft 63 beneath the rotary member or frame 60, Fig. 4, is a lever 83. At the free end of the lever 83 a link 84 is pivotally connected and the link 84 is also pivoted to one arm of the bell crank lever 85 carried upon the standard 42 and 43.

The other arm of the bell crank lever 85 carries a roller 86 and said arm and roller are normally disposed vertically but move radially away from such position when the lever 83 is moved downwardly by pressure on the operating lever 62. The crank lever 85 moves from the full line position shown in Fig. 4 to the dotted line position indicated in said Fig. 4. The roller 86, when in the full line elevated or normal position, shown in Fig. 4, engages with the under side of the cam element, or engagement arm 87 for retaining said cam elevated in the engagement and holding position shown.

A spring 88 is attached to the cam element or engagement arm 87 for elevating the same from the dotted line position to the full line position of Fig. 4. When the parts of the machine are in their operative position, the upper side of the cam element 87 supports a bar 89, mounting a clamp or pressure foot, to be described, carrying a roller 90 at its lower end. The bar 89 is slidably mounted upon the face of a circular plate, to be described, between the angle bar 92 and the body of the plate, as seen in Figs. 10 and 11. The roller 90, when in the projection shown in Figs. 10 and 11, rides over the upper edge of the cam element 87 during final rotation of the rotary member 61 for elevating the sliding bar 89 to the full line position shown in Fig. 4, and the roller 86, prior to

such time, rides under said cam element for retaining the same in operative position to cause such elevation of the sliding bar 89. Thus it is seen that the bell crank lever 85 and the cam element 87 cooperate to support the sliding bar 89 in operative position.

Reference should now be made to Figs. 8, 10, 11, and 12, showing the construction of one of the bundle holding and supporting end rotary members. Both bundle holding and supporting end rotary members being exactly alike, a description of one will suffice for both.

The body of the bundle holding and supporting end rotary member 61 is a circular plate having an annular flange 91. Secured to that face of said circular plate opposite the annular flange side thereof, is a bundle supporting annular bar 92, which provides a fixed support against which a bundle is clamped or pressed by the sliding bar 89.

A bracket 93 is attached to said bar 89 and 20 to which bracket an actuating spring 95 is attached at 94, and by reference to Fig. 4 it is seen that said spring 95 is under compression between said bracket 94 and the structure 59, at 96 of Fig. 11. Thus the spring 95 is held 25 against displacement and operates through the medium of the bracket 93 to force the sliding bar 89 downwardly so that the roller 90 will project beyond the periphery of the circular plate, as seen in Figs. 10 and 11. By reference to Fig. 8, 30 it is seen that the longitudinal axis of the spring 95 is offset with respect to each the sliding bar 89 and the center of the circular plate 61.

The upper half of the bar 89 is preferably made dove-tailed in cross section, as seen in Fig. 12, to fit into a correspondingly shaped groove provided in the face of the structure 61. This dove-tailed section 97 is slotted, as indicated at 98, Fig. 10, to receive bolts or the like 100, which adjustably secures the jogger clamp 99 to the 40 sliding bar 89. The slots 98 extend a considerable distance of the length of the dove-tailed section 97, and throughout that length the clamp 99 may be adjusted as is obvious from the disclosure of Fig. 10. When the sliding bar 89 is 45 moved upwardly, or downwardly, guided by the dove-tailed groove, it carries with it the clamp 99. By reference to the clamping structure shown in Figs. 10, 11, and 12, it will be obvious that the jogger or presser foot 99, and the sliding bar 89, are free to move quickly to strike a sharp blow under the action of the spring 95 in a downward direction when the edge of the cam 87 recedes and that the said clamping structure is free to move against the tension of said 55 spring 95 when the roller 90 reaches and rides upwardly on the elevating edge of the cam element 87.

The spring 95 not only serves as a power factor to firmly hold the bundle on the support, by 60 the force exerted on the sliding structure 89, 90, and 99, but it also provides for compensatingly clamping and holding bundles of varying dimensions, within the limits of actuation or yieldability of action or movement of the spring 95. 65 This compensation feature eliminates the employment of unyieldable clamping means having a definite distance of travel not adapted to compensate for bundles which vary in dimension. As will be obvious to anyone skilled in the art, 70 the resiliency of the spring 95 provides adaptation to varying sizes of bundles without requiring clamping adjustment for each size as is necessary in devices having no yieldability and a positive distance of clamping travel or stroke.

The adjustable bundle abutment means of this invention will now be described and the new and useful disclosure and object of such adjustable bundle abutment means will be apparent from such description and the showing of the drawings and appended claims.

It will be understood by those skilled in the art, that bundle binding machines of the prior art have been designed for the binding and tying of bundles of limited dimensions, and therefore fixed abutments have been the order. This invention is adaptable to all requirements and conditions of service in connection with bundle binding machines by providing abutment means adjustable relative to the support for locating the bundle in proper binding and tying position, irrespective of the size thereof within the capacity of the machine.

It will be apparent that the use of the adjustable abutment means providing for the location of various size bundles in proper binding and tying position, when used in the same machine in connection with the novel bundle clamping means providing for the clamping of various size bundles within the range of movement of the clamp, without requirement of adjustment of the clamp, provides a novel and useful combination representing a material advance in this art, and I intend to claim the same in its broadest possible scope with respect to binding machines.

The clamping element, or jogger, 99 is shown as preferably of angle bar construction, but the design thereof may be of any well known shape or adaptability. Said element is slotted at 101, Fig. 12, on the horizontal flange thereof, to provide for the receiving of, and the adjustment of, a bundle registering abutment, backwall, or jaw, 102 which serves to register a lower edge of the bundle 107, Fig. 4, in predetermined tying register with respect to the predetermined location of the tying means 189, and said abutment also serves as a backwall against which the operator may quickly place the bundle directly into binding and tying register upon the bundle support 92. The adjustable abutment, or jaw, 102 has an arm 103 and is adjustable along the T-slot 104 provided in the rotary element 61, parallel to and between the elements 92 and 99. Bolts 105, or the like, have heads fitting into said slot whereby the abutment, or jaw, 102 may be held in any desired adjusted position. The numeral 106, Figs. 4, 11, and 12, designates the slotted piece or bolt which is adjustably attached to the clamp, 99 to assist in holding the adjustable abutment, or jaw, 102 in proper alignment.

Running longitudinally of the machine near the base thereof and parallel with each other are two screw-threaded shafts 108 and 109 whose purpose is to effect adjustment of the lateral spacing of the various standards or tying or uniting units of the machine. The shaft 108 is supported at one end in a bearing 110 provided on the fixed standard 42, while its other end turns in a bearing 110 secured upon the base. This shaft 108 is provided with a squared end 111 so that it may be turned by a crank or wrench or similar tool. The adjustable standard 43 engages with the screwthreaded shaft 108 by means of a threaded collar 110 secured thereto. Turning of the shaft 108 will cause the standard 43 to move toward or away from the fixed standard 42 according to the direction of rotation. The other screw threaded shaft 109 also turns in the bearing 110 near one end and that end is made squared as shown at 112, Fig. 3a.

The function of the screw-threaded shaft 109 is to cause lateral adjustment of the intermediate chucks whose standards 113 are slidably supported upon the base of the machine. The screw-threaded shaft 109 engages with the standards 113 and when turned causes movement of said standards and with them the intermediate rotary members 120 either toward or from the fixed end rotary member 61. By reference to Fig. 35 it will be obvious that, when no such rotary elements as 60 and 61 mounted on the standards 42 and 43 are employed, the standards 113 may be arranged as adjustable with respect to each other in any desired manner, and further with respect to the showing of Fig. 35, it will be obvious that each of the standards 113 may be spaced apart to such extent that the binding and tying, and clamping features mounted and arranged upon, and with respect to each standard 113, may be considered as constituting a complete binding and tying unit or machine of itself. It is to be understood from the disclosure of Figs. 1 and 35, and the reading of the specification, that this invention contemplates and discloses such unitary assembling of wire binding and tying and clamping features on the respective standards 113 as provides for each of said assembled units constituting of itself a complete and operable wire binding and tying apparatus, and that each of said units assembled with respect to each of the standards 113 is independently operable with respect to the supporting, clamping, binding, and tying of a bundle, and may be employed in several and distinct machines if so desired.

The rotary members, having bundle receiving openings, and associated parts will now be described (see Figs. 5, 6, and 7). The drive shaft 53 carries a splined gear 114 which meshes with similar gears 115 and 116, both of which turn about supports secured to the standard 113. The gear 115 rotates the bundle holding frame or carrier as will be described. The gear 116 is an idler and meshes with another idler 117, which meshes with a second member or carrier turning gear 118.

Each rotary member having a bundle receiving opening is composed of plates 120 between which a segmental gear 121 is secured, see Figs. 6 and 13. It will be readily seen from the figures referred to that the plates 120 and the gear 121 are so united as to constitute a singular rotary member, or frame, or carrier and that said plates and gear may be cast or made as of one piece, if so desired. Said rotary members, which for convenience of description will be referred to by the numeral 120, are guided and supported so as to rotate preferably in a vertical plane by means of flanged rollers 119 secured at intervals upon the standard 113. The rotary member 120 (Figs. 5, 6, and 7) has an opening 122 in the periphery thereof which permits a side-wise movement of a bundle 107 into and out of tying location within the circumference of the rotary member 120 when said rotary element is in its bundle receiving and bundle discharging position.

As will be seen in Figs. 6, 7, and 8, the drive shaft 53 turns the rotary member 120 by means of the drive gears 114, 115, and 116, except when the opening 122 is opposite one of said drive gears, in which event the other drive gears 117 and 118 (see Fig. 6) will continue the rotation of the member 120, by reason of the spacing apart of the gears 115 and 118 being greater than the bundle receiving opening 122 of the 75

member 120. The spacing of the rollers 119 is such that the member 120 is always in engagement with at least three of said rollers and with one of the driving gears. The idlers 116 and 117 cause rotation of the gears 115 and 118 in the same direction.

The clamping mechanism of Figs. 5, 6, 7, and 9 will now be described.

The rotary frames 120 have jogger type bundle clamping means of the nature of the clamping means hereinafore described, and varying somewhat therefrom as to certain particulars which will now be described, (see Figs. 6 and 7). The lever pivot shaft 63 has arms 123 slidably mounted thereon to be adjustable along with the standards 113, there being one arm 123 for each of said standards. The other end of arm 123 has secured thereto a flexible element 124 which passes over an arcuate guiding sheave 125 rotatably mounted upon the standard 113. The flexible element, which may be a cord, or cable, or chain, is passed around a pulley 126 whose pivot is secured to the standard 113. The other end of the flexible element 124 is secured to a rod 127 which is vertically slidable in a guide element 128 on standard 113 which has a bifurcated end 130, which carries a roller 131 mounted between the furcation of said rod 127. A coil spring 129 is mounted on the rod 127 between the element 128 and the shoulder of the bifurcated end 130. The function of said spring 129 will be best understood as hereinafter set forth in the description of its operativeness in connection with the operation of the clamping mechanism.

A stationary element 132 is attached to the standard 113 above the upper end of rod 127 and the lower end thereof is provided with a roller 133 adapted for holding the roller 131 in positive engagement with the rotatable cam element 134 to prevent said cam element from receding when the projecting roller 137 attached to one end of the arm 136, in moving from the position shown in Fig. 9 to the normal position of Fig. 7. The cam shaped element 134 is pivotably mounted on the standard 113 and has attached thereto a spring 135 adapted and arranged to move the said cam into the path of travel of the projecting roller 137 (see Fig. 9). In Fig. 7 it is shown that the roller 131 is moved into holding and engagement position between the stationary roller 133 and said cam 134 by the tension spring 129, thereby rigidly holding said cam in position for depressing the roller 137 and through said process elevating the clamp against the tension of the springs 146.

The operation of the clamping mechanism is as follows: Assuming the parts are in the position illustrated in Figs. 5, 6, and 7, foot pressure on the lever 62 transmits rotation to the shaft 63, which in turn actuates the elements 123 and 124, to pull the rod 127 and roller 131 downwardly against the resistance of the tension spring 129, thereby effecting controlled release of the cam element 134 in such manner that said cam element 134 recedes under pressure of the arm 136 and roller 137, (which pressure is provided by the springs 146) until the arm 136 has moved sufficiently to insure the clamping of the bundle by the clamp 147 and the projection of the roller 137 beyond the periphery of the rotary frame 120, (see Fig. 9) for engagement with the cam element 134, when said cam element is restored to the initial position by the action of the spring 135 operatively connected therewith, and during the 75 rotation of the frame 120. Said cam element 134

being held in said position by the force and resistance of the tension spring 129, and which tension spring 129 also functions to restore the lever 62 and the roller 131, to the initial positions, during rotation of the rotary frame 120, by lifting the rod 127, which in turn will pull on the flexible element 124 and arm 123 to effect said result.

In Figs. 5, 6, and 7, provision has been made for damping the action of the clamp 147 to compensate, control, or dampen, the striking force of 10 said clamp with respect to different sizes of bundles within the range of movement of the clamp, to prevent injury to the material, or bundles, and particularly so when the clamp moves a greater distance in the clamping of a 15 small bundle. This damping action is clear from the showing of Figs. 5, 6, and 7, wherein the tension spring 129 resists the downward movement of the roller 131, as the cam element 134 remains in contact with the convex face of said 20 roller 131, to damp the action of the roller 137 and elements 136, 139, 140, 142, and 147, for the major portion of the clamping action, as the roller 131 is lowered to provide the clamping of 25 the bundle. It is further to be noted, in said 30 Figs. 5, 6, and 7, that the arm 136 partakes of a radial follow-up contacting movement with respect to the receding of the cam element 134, thereby avoiding abrupt disengagement with the cam element 134, and cooperating to damp the 35 action of the clamp 147.

The arm 136 is pivoted at 138 on the rotary frame or member 120, see Fig. 7. The opposite end of the arm 136 is pivotally connected with a link 139, which link in turn is pivotally connected with a lever 140. The lever 140 turns on a pivot 141, as shown in Figs. 7, 9, and 13 and connects at its upper end with a link 140a provided at each side of the rotary frame 120, and each link 140a having its ends attached to upright rods 144 slidably mounted in the respective elements 143. Each rod 144 passes slidably through the brackets 145 integral with the rotary frames 120, and each slidable rod has a coiled spring 146 surrounding the same and interposed under tension 45 between the brackets 145 and the link 142. The lower end of each of the rods 144 is secured to clamp 147 and which bundle clamp 147 is shown in clamping position under the tension of the 50 springs 146, in Fig. 9.

From the showing of Figs. 1, 2, and 4 to 14, inclusive, it will be readily understood by those skilled in the art that each of the elements 92 and 147 function as a jaw, or clamp, or presser foot, or jogger, or jogger clamp, and that it is proper to so designate said elements in the specification and the appended claims for the purpose of safeguarding and describing the new and useful disclosures of this part of the invention. In explanation and support of such designations it 60 is submitted that the terms "jaw" or "clamp" are proper when used to indicate the element which clamps and holds the bundle; and that the term "presser foot" is proper when used to indicate the pressing or compacting of the bundle 65 by the "jaw" or "clamp" against a fixed element; and that the terms "jogger" or "jogger clamp" are proper when used to indicate the jogger action of said jaw, clamp, or presser foot.

As shown in Figs. 5, 6, and 7, the shape of the 70 assembled plates 120 and the gear 121, which constitute the designated rotary member or frame 120, is that of a frame upon which the bundle support, the abutment, the clamping means and knotter mechanism and associated parts are 75

mounted. In the figures referred to the frame is shown surrounding three sides only of the bundle, to provide for sidewise movement of the bundles into tying location.

5 In Figs. 1, 2, and 4 to 7, inclusive, it is to be noted that the tensioning means provided puts a sufficient tensioned pull on the wire, and so convexly tensions the wire, that as the wire is applied it will effect tight hugging or compacting of a bundle, or series of boards, or box shocks, and the like, without requiring the clamping means for such effect, and in which event it will be understood that the clamp may be arranged to operate against either the side or the top of the bundle as aforementioned.

As shown in Fig. 5 the lower part of the rotary frame 120 carries the knotter mechanism to be hereinafter described. The rear portion of the rotary frame 120 supports an adjustable abutment, or jaw 148, similar to the adjustable abutment 102 which has heretofore been described. The adjustable abutment, or jaw 148 has an arm 149, and bolts 150 are provided which pass through said abutment and have heads fitting into the T-slot 151 which runs parallel between the elements 143 and 152. The elements 152 are fixed bundle supports, or jaws, entirely analogous to the fixed bundle supports, or jaws 92 of the members 60 and 61. Although the adjustability of the abutment 148 is shown as considerably less than that of the abutment 102, it is obvious from the drawing of Fig. 5 that the arm 149 may be considerably lengthened to provide for adequate adjustment of the abutment 148, or fillers may be employed between the abutment 148 and very small bundles.

By reference to Figs. 7 and 35, it is seen that the end rotary members 60 and 61, may be dispensed with and the machine still will be operative in every sense to effect the binding and tying of a bundle; and it will be particularly noted that when the machine is employed as shown in said Figs. 7 and 35, the bundle 107 may be fed into binding and tying position either in sidewise movement or in lengthwise movement, and consequently that whereas the abutments 148 provide a backwall against which the bundle is placed in sidewise movement, said abutments also provide a guide fence for guiding the bundles when the same are advanced in lengthwise direction directly into binding and tying location on the support. Therefore it is obvious that the abutments shown in this machine may be employed either as a backwall or guide fence in accordance with the manner in which it is desired to place or advance the bundles into binding and tying location.

The tension device shown in Figs. 1 to 7 inclusive, and 31, will now be described, and a primary object of this feature of my invention is to provide machines capable of wrapping a wire around a box or bundle, with means for convexly tensioning the wire so that the wire will lie flat against the respective faces of the bundle in such manner that when the tensioned wire wrapped and tied about the bundle is cut open the wire will normally, under the convex tension stress therein, curve convexly toward the axis and sides of the bundle, such manner of convex tensioning causing the wire to lie flat against the side of the bundle when applied thereto. The present tension device is designed especially for wire.

A modification of this tension device designed for use with flat metallic bands is described and

claimed in an application filed of even date herewith, Serial No. 380,376. The tension device shown in Figs. 4 and 5, includes a frame 155, consisting of the elements 155 and 165, secured by the bolt 158 to the supporting standard 113 upon which is mounted means for convexly tensioning the wire. As seen in Figs. 1 and 2, each of the intermediate standards 113 carries a pair of these tension devices while each of the standards 42 and 43 carries a single tensioning device. In each instance the frame 155 is secured to the adjacent standard, preferably at an angle inclined to the vertical for the purpose of permitting compactness of machine design, as shown in Figs. 4 and 7, inclusive. The frame 155 is fixed to a bolt 159 which provides a support for the reel 156 containing the wire 157. The bolt 159 carries a friction disk 160 (see Fig. 31) with which the inner or standard face of the reel frictionally engages. This friction disk 160 may be of hardwood or the like. Also mounted on the reel support 159 is an outer friction disk 161 having a cap 162, against which bears the tension coil spring 163 mounted on the reel support 159. The end of the bolt 159 is screw-threaded to receive the tension adjusting nut 164, which when turned will regulate the pressure of the tension spring 163 upon the friction disk 162 whereupon the friction between the reel 156 and the friction disks 160 and 162 will be likewise regulated as desired to retard free turning of the reel 156.

The upper end of the frame 155, as shown in Fig. 1, is U-shaped to provide a support for the bolt 166, Fig. 31. Upon the bolt 166 is mounted the inner friction disk 167, the rotary tensioning wheel 168 which convexly tensions the wire, and the outer friction disk 169. The cap 170 fits over the outer friction disk 169 and receives pressure from the tension coil spring 171 mounted on the outer end of the bolt 166. The outer end of the bolt 166 is screw-threaded to receive the tension adjusting nut 172, which when turned will vary the pressure of the friction disks against the sides of the tension wheel 168 for retarding the rotation of said tension wheel in the manner desired to insure convexly tensioning and wrapping the wire in tensioned state tightly about and tightly against the sides of the bundle. The wire, or binder, 157, is delivered under tension (see Fig. 3) and passes from the reel 156 and is preferably passed around the wheel, or roller 168, one or more turns, (see Fig. 2) to provide for delivery and application of the wire, to and about the bundle, in convexly tensioned condition. In Figs. 4, 4a, 5, 6, 7, and 36 to 39, inclusive, it is seen that the means, or member 168 contacts the wire to flex it away from the bundle in the plane of the wrapping of the wire and during the entire wrapping movement. This, coupled with the tension of the wire, causes convex flexing, or convex tensioning thereof, and thereby results in the wire tightly hugging the sides of the bundle. In this connection, it is to be observed that the means 168, forms a lead-off guide member for the wire, and is interposed between the gripper 195 and the tensioning source, 156, 161, 162, and 163. From the wire tensioning wheel 168 the wire extends to the wire uniting or knotter mechanism which is mounted in substantial alignment therewith, and which knotter mechanism will be hereinafter described with its operating mechanism. From the aforesaid description, and from the showing of Figs. 1, 2, and 31, it is seen that any desired tension may be put on the wire or binding element, the

degree of the tension depending upon the turn, or turns, or wrap, or wraps, of the wire or binding element about the convexing tension wheel 168 and the retarding of the rotation of said wheel and the reel 156. It will be seen from the drawings that the frictionally retarded reel 156 of itself provides sufficient tensioning of the wire to insure tensioned binding of the bundle with the wire, and that the function of the tensioning wheel 168 is primarily that of convexly tensioning the wire for the application thereof in a convexly tensioned state about the bundle.

The mechanism for uniting the terminals of the binding element will now be described.

15 As shown in Figs. 2, 4, and 7, the rotary members 60 and 120, respectively, mount binder terminal uniting mechanisms of like character. Each rotary member carries a spider 173 having four arms, the ends of which arms successively 20 extend beyond the periphery of the member as the member is rotated. The element which carries the spider 173 also supports a gear 174 meshing with a pinion 175. Each rotary member support, or standard, carries a roller 177 disposed in 25 such position that it will engage one of the arms of the spider when the member is rotated, see Fig. 21. When the arm of the spider engages with said roller during rotation of the member the roller causes the spider to rotate, which in 30 turn causes rotation of the knotter head, as will be described.

As shown in Fig. 5, the rotary members 120 carry spiders 208 in a position different from the position of the spiders 173 on the rotary members 60 and 61, as represented in Fig. 4. Since the knotting mechanism of the end rotary members is precisely the same as the knotting mechanism of the central rotary members a description of one knotting mechanism will suffice for all.

40 It will be seen from Figs. 1 and 2 that the end rotary members carry a single knotting mechanism just as they carry a single tensioning device, while each intermediate rotary member carries a pair of knotting mechanisms, one on each side 45 of the rotary member. Each spider 208 has secured thereto a gear 207 meshing with a similar gear 206, in turn meshing with the pinion 175. The standards 113 carry a bracket 210 having a roller 209 which engages with the arms of the 50 spider 208 in precisely the same manner as the roller 177 engages with the spider 173. While there are two binder uniting mechanisms mounted on each rotary member 120, but one spider is required to actuate both mechanisms, since as 55 shown in Figs. 2, 5, and 7, the gear wheels 176 which actuate the knotter heads are mounted so as to rotate in unison on opposite sides of the rotary member 120.

Reference should now be made to Figs. 21 to 60 25 inclusive. Here it is seen that the pinion 175 when rotated turns a bevel gear 176, which bevel gear also carries a grooved cam plate 178. This cam plate has a groove 179, the purpose of which is to move the knotter head longitudinally, as 65 will be described. A roller 180^a (see Fig. 25), secured on the end of an arm 180, is received by the cam groove 179, and when the bevel gear 176 is rotated causes reciprocation of the arm 180. The upper end of the arm 180 carries a frame 181 70 slidably mounted on parallel rods 182 fixed in vertical positions in a knotter frame 188. Springs 183 are mounted on each rod 182 so as to give to the frame 181 normal tendency to move upwardly. A wire guiding roller or spool 184 75 mounted on the frame 181 directly beneath a

knotter head 189 which is rotatably mounted in the frame 188. The knotter head is movable longitudinally, a ring 190 integral with the frame 181 fitting about the lower end of said head (see Fig. 25). Said ring has a break in its as shown at 190^a in Fig. 21.

A stub shaft 186 is mounted upon the frame 188 so as to rotate about a vertical axis and carries a pinion 185 meshing with the bevel gear 176. The upper end of the stub shaft carries a knotter 10 drive gear 187 which meshes with a knotter head gear 181 preferably formed integrally with the knotter head 189. The knotter head gear is provided intermediate the ends of the knotter head and has a diameter greater than the knotter 15 head but equal to that of the pinion 187. The upper side of the frame 188 carries a cutter strike roller 193 which engages with a cutter 198 pivoted upon the upper end of the knotter head, when the latter has been rotated and moved downwardly into the position shown in Fig. 25. See also Figs. 28 and 29. The knotter head is slotted longitudinally as indicated at 192 and the slot registers with a similar slot provided in the gear and with the break 190^a in the ring 190. This 20 slot is provided for the purpose of receiving a wire to coil or twist the same about a terminal thereof. A wire receiving socket or bore 194 is provided to run longitudinally of the knotter head. If a coil is to be made the wire receiving 30 bore 194 will coincide with the longitudinal axis of the cutter head, as shown in Figs. 28 and 29. If a twist is to be made, the wire receiving bore will lie to one side of the axis, as shown at 202 in Fig. 30. In either case the wire when inserted 35 in said bore is gripped by blocks 195 having teeth projected into said bore and adapted to engage wire. A spring 196 normally presses the block so that its teeth will project into the bore and a screw block 197 is provided to adjust the 40 tension of the spring 196. The wire is bent at right angles, as shown at 203 in Fig. 22, and its end is inserted into the bore 194 where it is gripped by the teeth of the block 195, as shown in dotted lines in Fig. 22.

The cutter 198 has a knife edge 199 and has a length such that it extends beyond the periphery of the cutter head (Fig. 28). The extending end of this cutter causes it to engage with the strike roller 193 when the knotter head has been moved from the position of Fig. 21 to that shown in Fig. 25. A spring 200 normally holds the cutter in the position of Figs. 23 and 28; but when the strike roller engages with the cutter as shown in Fig. 29, the latter will be moved across the slot 192, thereby severing the wire in said slot. One half of the upper end of the knotter head is depressed, as indicated in Figs. 25, 28, 29, and 30, to permit oscillation of the cutter about its axis, while not engaging with the wire inserted in the bore 197.

In Figs. 26 and 27 two forms of the cams for moving the knotter heads longitudinally during their rotation are shown. Each of the cams 179 and 201, are so formed that after the completion of the coil or twist the knotter head is quickly elevated and returned to normal position prior to the completion of the cycle of rotation of rotary gear 176 and the knotter head respectively, and it will be readily understood that upon the return upward movement the rotating knotter head engages the end of the formed tie and bends or presses the tie against the lower face of the bundle. In Figs. 22, 26, and 27, it is seen that the elevation and return of the knotter head is made 75

so quickly by the cam that there is but sufficient rotation of the knotter head to provide for deflecting the formed tie to a degree whereby the same will be easily pressed to place against the lower face of the bundle as the head elevates, and returns to its normal or starting position shown in Fig. 22. The cam of Fig. 26 might be called a twisting cam, since it is designed to be used with a knotter head which will form a twist 10 against the corner of the bundle, as shown at 212 in Fig. 34. In the case of a twist the cam causes withdrawal of the knotter head from the bundle simultaneously with the beginning of its rotation. The cam groove 201 of Fig. 26, which 15 will be described, is so formed as to give rise to this immediate withdrawal.

The coiling cam, shown in Fig. 27, with its groove 179 is so formed as to permit the first coil to be formed against the bundle before any longitudinal movement is imparted to the knotter head. It will be observed that the groove 179 is concentric with the cam plate 178 for approximately a quadrant. Thus the first coil will be formed, as shown at 211 in Fig. 33, lying snugly 25 against the bundle. In my Patent 1,295,531, Re-issue 15,111 I have described and claimed broadly means for forming a coil knot against a bundle.

Figs. 28 and 29 illustrate a knotter head whose wire receiving bore 194 is concentric therewith. The wire receiving bore 202 of Fig. 30 is off center with respect to the knotter head. It results that the use of the knotter head 189 causes that portion of the wire which is in the slot 192 to be coiled about the end 203 of the wire. The end 203 being placed in the exact center of the rotary knotter head has no motion imparted thereto and is therefore stationary when the other section of the wire is coiled about it; but in the case of 40 the knotter head 189, Fig. 30, the end of the wire which is held in the bore 202 is off center. Furthermore that section of the wire which is in the slot 192 is off center. The result is that when the knotter head 189 is rotated both portions of the wire will be twisted about each other. The knotter head 189 might therefore be entitled a twisting knotter head. It will be clear that by changing the cam plate and the knotter head, the machine of the invention may be 45 changed from a coiling to a twisting machine without other modification. As the knotter head is moved longitudinally during either the coiling or the twisting, and as the band is placed under tension about the bundle, the effect of either the coiling or the twisting will be to pull the free end 203 of the wire out of the bore 194 or 202, as the case may be, and when the coil or twist has been finished, the wire will be free of the 50 knotter head and will assume the position in relation to the bundle shown in Figs. 33 or 34.

In Figs. 21 and 22, it is to be noted that the normal position of the knotter head is elevated and adjacent the bundle, whereas in Figs. 25 and 39, 55 at the time of completion of the twist or coil the knotter head is in lowered position. By reference to the showing of gear ratios of the gears 174, and 175, Figs. 1 and 25, it is seen that said knotter head continues to rotate after the formation of the tie until it is elevated or returned to normal position. The effect of this continuous operation and elevation of the knotter head, after completion of the tie, is to strike and deflect the free end of the tie from its completed position upwardly until the tie lies against the face of the

bundle, and out of the projecting relation in which it was formed.

In Fig. 32 the tension arm 155 is shown provided with a wire guide 213 having a slot 214 adapted to receive the wire. The function of this wire guide is to place the wire on the tension wheel in the proper position so that it will always lead off to the knotter head in a true line. The wire must not deviate from this line to any marked degree; otherwise when the chucks are 10 rotated, carrying with them the knotter heads, the wire will not properly engage with the roller 184 and will not pass into the slots 192.

Figs. 4a and 5a represent the wire tensioning device oscillatively mounted for convexly tensioning and applying the binding element about the periphery of the bundle in such manner that the wire will under its convex tension contact with and lie flat and tightly about and against the periphery of the bundle. Figs. 36 to 39, inclusive, 15 show the oscillation of the binding member 155 as the tensioning wheel 168 convexly tensions and applies the wire about the periphery of the bundle, and wraps the wire into the knotter mechanism. Such oscillating means may take any mechanical form. In the form shown in Figs. 4a and 5a, a pinion 215 on the shaft 53 meshes with a gear 216 rotatably mounted on the standard. A pinion gear 217 is fast to gear 216 and meshes with a gear 218, and the latter is fixed upon a support on the standard and carries an eccentric 219. The eccentric has a link 220 pivotally connected to the binding member 155, mounted to oscillate on the axial element 159. The tensioning wheel 168, about which the wire 20 is wrapped one or more turns for convex tensioning thereof with respect to the axis and periphery of the bundle being rotatably mounted on the oscillatory binding member.

As Figs. 36 to 39, inclusive, indicate, the eccentric oscillating the binding member 155 in such manner that after the rotary member 60 is rotated approximately a quarter of a turn, the tension wheel 168, which functions to impart convex tension to the wire and wraps it about and against the sides of the bundle and is frictionally retarded, occupies a position near the periphery of the rotary member 60 whereby the tension of the wire is less than that obtaining when the bundle has been completely enclosed with the wire, as indicated in Fig. 37. In Fig. 37, it is seen that the binding member has oscillated to its extreme operative tensioning position and at which position the tension of the wire is at the maximum. This moment of maximum tensioning occurs at about 30 the time the wire has been laid about the fourth side of the bundle and has been wrapped into the slot of the knotter head.

The same effect which the oscillating tension arm produces will be reached by changing the center of rotation of the chucks. If the center of the chuck is offset sufficiently a stationary tension device, as shown in Figs. 1, 2, 3, 3a, 4, 5, 6, 7, and 31, may be employed. The center of rotation of the rotary member can be so selected that the effect of any neutral point, in allowing the wire to become slack when a very small bundle is being bound, will be overcome.

Fig. 35 illustrates an embodiment of the invention in which three open-throated rotary members are used, the end rotary members being eliminated. However, one or any other greater number of such rotary members will comprise an operative machine, since obviously the width of a single frame, having a bundle receiving opening,

may be made sufficient to accommodate an entire bundle of commercial size. The machine of Fig. 35 will handle bundles of any length because of the open throats of the rotary members. Bundles of unequal lengths may also be handled readily and it will be obvious from the showing of Fig. 35 that either a long bundle extending lengthwise between either two or three of the binding and tying units, mounted on the standards 113, may be 5 banded, or bundles of lesser length may be bound separately by each or any one of standards 113; the machine of this invention being adapted to place either one or two bands about a bundle with the employment of the binding and tying 10 unit of a standard 113 only, and with which singular unit would constitute, in connection with the necessary power driving mechanism, a complete, practical and operative bundle binding and tying machine.

15 20 The operation of the machine will now be described. The ends of the wires 157 are led from the reels over the tension wheels and are inserted into the wire-receiving bore in the knotter head, being bent at right angles, as indicated in Figs. 4 to 7, inclusive, and 22. This forms a kink in the wire which by itself will hold the wire, and with the aid of the spring-pressed gripper block 195 the wire is securely held within the knotter head. The bundle is placed in the machine, resting upon the lower jaws or bundle supports 92 and 152. One or more bundles may be 25 so placed. If a plurality of bundles are inserted in the machine at one time they may be set end to end. Then the operator presses down on the 30 foot lever 62 which first causes simultaneous clamping of the bundle or bundles by the clamping jaws 99 and 147 and the projection of the rollers 90 and 137. Further pressure on the foot lever will bring into effect the release of the clutch 35 pin, whereupon the drive shaft is rotated. The rotary members will be simultaneously revolved on a common horizontal axis carrying with them the bundle or bundles which are also rotated on a common horizontal axis. As the bundle or bundles are rotated the wire strands will be wrapped about the same at desired intervals according to the lateral spacing of the rotary members from each other, and also according to whether the intermediate chucks each have one or both of their 40 knotter heads threaded with the wire. Prior to the completing of the banding operation the roller 90 rides over the elevated cam shaped element 87 thereby elevating the rod 89 and the clamping member 99 to release the bundle and to provide 45 the space necessary for receiving the subsequent bundle to be bound. When the bundle or bundles have nearly reached their original position, the spiders carried by each rotary member will rotate the knotter head, forming a coil or twist, as the 50 case may be. This action is best understood from Figs. 38 and 39. The knotter heads on both the end and the open-throated rotary members are simultaneously actuated and the coils or twists are simultaneously formed at the lower corner 55 or corners of the bundle or bundles.

It is to be understood that although I have shown a type of knotter mechanism adapted to form the tie, or twist or coil, at the corner of the bundle, such showing is only for the purpose of 70 illustrating the practical application of my invention for the binding of bundles, and it is my intention that the scope of this invention shall contemplate the use, or employment, or substitution of other adaptable types of tying mechanisms. The foot pedal is released immediately 75

the clutch engages and the clutch mechanism, functioning in the manner which has been described, will allow the parts to return to their original position. When this has taken place the cam elements 87, 134 being held in the paths of the rollers 90, 137, respectively, will cause the clamping jaws to elevate and release the bundle, as shown in Figs. 4 and 5. The bundle being now bound and tied, may be taken out of the machine. As will be clear from the drawings Figs. 10 4 and 7, the machine may be adapted so that the bundle or bundles may be moved either lengthwise or sidewise into and out of the machine.

By the time the wire has been enclosed about 15 the bundle, and the tie, or twist or coil, formed and pressed against the bundle, the roller 184, Figs. 21, 22, and 23, has drawn out sufficient convexly tensioned wire from the rotary tensioning and wrapping device 168 to provide for the 20 threading of the knotter 191 preparatory to the binding of the succeeding bundle.

The machines of the present invention are especially designed to handle bundles of loose material such as lumber or the like; but by merely 25 eliminating the knotter mechanisms the machines become adaptable for handling boxes, or the like, and placing bands other than round wire about the same. Such modifications of the present machine are described and claimed in an application filed by me of even date herewith, Serial No. 380,376.

The special feature of the machine of the present invention is its high degree of adaptability 30 to all conditions of service. It will handle either compressible or incompressible units or bundles, or bundles of loose material or articles of a definite form and will place any desired number of bands about the same, the bands being wrapped under a constant tension regardless of the size 35 of the bundle or article. The peculiar construction of the open-throated rotary members, with their double clamping jaws, the two knotting mechanisms, and the two tensioning devices, makes it possible to handle two or more bundles 40 at the same time with the same machine. It is also possible to bind a bundle held by one of the open-throated rotary members with one or two bands alone. A bundle may also be held by either 45 end rotary member and by one of the open-throated rotary members. With two open-throated rotary members employed in cooperation with two end rotary members as illustrated in Fig. 1 it is possible to bind three bundles at the same 50 time, the bundles differing widely from each other in their dimensions. A bundle may be held by the fixed end rotary member and the nearest open-throated rotary member. A second bundle may be held by the two open-throated rotary members. A third bundle may be held by the 55 adjustable end rotary member and the open-throated rotary member nearest the same. If three or more open-throated rotary members are employed it will be clear that four or more bundles placed end to end could be handled at the same time. If a single bundle is to be bound and if the machine is as shown in Fig. 1, as many as six strands may be wrapped about the same simultaneously and their ends coiled or twisted as 60 desired. This operation will take place when both the knotter mechanisms of each open-throated rotary member are threaded. However, the bundle may be bound at its ends only by the 65 mechanisms associated with the end rotary mem- 70 75

bers and any one of the open-throated rotary members.

From what has been said it will be clear that the present machine is capable of being used under widely varying conditions of service. When I employ the term "open mouthed" with respect to the bundle holding frames of Figs. 5, 6, and 7, such term is employed only for convenience of reference to the bundle receiving opening having the break 122 for receiving bundles in sidewise movement into tying location, and such term is not to be considered in any restricted sense, for my invention is of broad scope and contemplates the employment of bundle receiving frames adapted to receive bundles into tying location in either sidewise movement or lengthwise movement, or in sidewise movement only, or lengthwise movement only.

When I use the term "units", in connection with the machine structure itself, I refer to the several bundle binding and tying entities comprising the respective standards 42 and 43, and the several standards 113, and the bundle binding and tying mechanisms mounted thereon and associated therewith.

When I use the terms "compensate" or "compensating" or "compensatingly" with reference to the clamping means disclosed in this invention I have reference to the self-adaptability or the self-adjustability of the clamping features whereby variable distance of movement of the clamp is provided for with respect to the pressure holding of varying sizes of bundles, within the limits of yieldability, or compression or expansion of the clamp actuating means. In the specification and claims, for the purpose of brevity and reciting the method of flexing or curved processing of the wire to accomplish convexed tensioning thereof, I have found it desirable to employ terms original with me. When I use the terms "convex tension", "convex tensioning", "convexly tensions", "convexly tensioned", or words or terms of such import, with reference to the wire, I have reference to that tension imparted to the wire by the rotary tensioning mechanism, as the wire is drawn out thereabout and thereover, and caused to flex or curve thereabout, before being wrapped about the bundle; and which tension becomes inherent in the wire so passed about and over the rotary mechanism, and causes the wire to lie flat and tightly hug the periphery of the bundle when wrapped thereabout; the proof and test of such "convex tensioning" being the convex form such inherent tension causes the wire to assume towards the axis and sides of the bundle, when the longitudinal tension of the wire drawn over the rotary mechanism or wrapped about the bundle lessens, or is relieved.

By the terms "band" or "binder" in the claims, I wish to comprehend either a wire as described in this application or an actual band as shown in my co-pending application Serial No. 380,376, or any binding element employed in bundle binding machines to which improvements of my invention may be adapted.

While I have shown a machine wherein are employed end rotary members and intermediate rotary members, it is within the scope of my invention to construct a machine formed of two end rotary members with no intermediate rotary members, or with one or more open-throated rotary members like the intermediate rotary members. In my co-pending application referred to I have shown the first-named construc-

tion and the claims in said application are directed to that specific adaptation of my invention.

While I have used the term "bundle" throughout this specification and claims as referring to the article acted upon, my invention is of much broader scope, as witness the fact that in my co-pending application the structure is employed in banding boxes. I do not therefore use the term "bundle" in a restricted sense.

Obviously the present invention is not restricted to the particular embodiments thereof herein shown and described. Moreover, it is not indispensable that all the features of the invention be used conjointly since they may be employed advantageously in various combinations and subcombinations as defined in the claims.

What I claim is:—

1. A machine of the class described comprising, in combination, means for supporting a bundle or other object of definite form and dimensions; adjustable means for clamping the bundle, means for rotating the bundle support; means for effecting wrapping of the bundle during its rotation with a plurality of bands; and means for independently uniting the ends of said bands.

2. A machine of the class described comprising, in combination, means for rotating a bundle or other object of definite form and dimensions; means for wrapping said bundle with a plurality of bands; means for adjusting the intervals between said bands; means for maintaining a substantially constant tension on each of said bands during the rotation; and plural means for uniting the ends of said bands during the rotation of the bundle.

3. A machine of the class described comprising, in combination, means for supporting a bundle or other object; adjustable bundle clamping means; means for rotating the clamped bundle; means for wrapping said bundle during rotation with a plurality of bands; means for adjusting the intervals between said bands; and means for independently uniting the ends of said bands.

4. In a machine of the class described, means for supporting a bundle, means for positioning the bundle on the support, means for retaining the same in binding position during binding, means for rotating the bundle, means for binding the bundle with a band, and means for tying the band.

5. In a machine of the class described, means for rotating a bundle, means for holding the bundle under compression as it is rotated, means for simultaneously wrapping said bundle with a plurality of bands, means for varying the intervals between the bands, means whereby said bands are wrapped at a constant tension, and means for independently uniting the ends of said bands.

6. In a machine of the class described, means for holding and rotating a bundle of definite form and dimensions, means for wrapping such a bundle with a band, and means for uniting the ends of said band adjacent one corner of the bundle.

7. In a machine of the class described, a rotary bundle supporting frame having a passageway for a bundle, a bundle support mounted thereon, means for positioning the bundle in tying location on the support, means for compressing and retaining the bundle against said bundle support, means for rotating the frame and the bundle, means for wrapping the bundle with a band, and means for tying the band.

8. A machine of the class described comprising, in combination, means for supporting a bundle, adjustable bundle clamping means, means for rotating a bundle of definite form and 5 dimensions on an axis coincident with or parallel to its longitudinal axis, depending on the size of the bundle; means for holding a band in such position that it will be engaged by the bundle during rotation to effect complete envelopment 10 of the bundle thereby; and means for uniting the ends of said band.
9. A machine of the class described comprising, in combination, means for clamping a bundle transversely at a plurality of points along its 15 length; means for rotating the bundle when so clamped; and means for wrapping a band about the rotated bundle adjacent each point of clamping.
10. In a machine of the class described, means 20 for clamping a bundle, means for rotating the bundle a single turn at a time, means for wrapping a band about the bundle during said rotation, and means for uniting the ends of the band prior to the completion of said turn.
11. In a machine of the class described, means 25 for clamping a bundle, means for rotating the bundle a single turn, means for wrapping a band about the bundle during said rotation, means for uniting the ends of said band prior to the completion of said turn, and means for releasing the bundle when it assumes its original position.
12. In a machine of the class described, means 30 for clamping a bundle, means for rotating the bundle a single turn, means for wrapping a band about the bundle during said rotation, means for holding the band at a substantially constant tension, and means for uniting the ends of said band before the completion of said rotation.
13. In a machine of the class described, means 35 for clamping a bundle, means for rotating the bundle a single turn, means for simultaneously wrapping a plurality of bands spaced at desired intervals from each other about the bundle during said rotation, and means for uniting the ends of each of said bands before the completion of said rotation.
14. In a machine of the class described, means 40 for clamping a bundle, means for rotating the bundle, means for simultaneously wrapping a plurality of bands about the bundle, means for adjusting the intervals between said bands, means for uniting the ends of each of said bands prior to the completion of said rotation, and means for releasing the bundle at the end of said rotation.
15. In a machine of the class described, a plurality 45 of rotary members, each member carrying means for clamping a bundle, means cooperating with each member for wrapping a band around the bundle, and means for uniting the ends of each band.
16. In a machine of the class described, a plurality 50 of rotary members, each member carrying means for clamping a bundle, means cooperating with each member for wrapping a band around the bundle, means for uniting the ends of each band, and means whereby the members may be spaced apart adjustable distances.
17. In a machine of the class described, a plurality 55 of rotary members, each member carrying means for clamping a bundle, means cooperating with each member for convexly tensioning and wrapping a band under such tension around the bundle, means for rotating said members simultaneously to effect binding of the bundle with a plurality of bands during each cycle of rotation of said members, means for uniting the ends of each band, and means for adjusting the members relative to each other to provide determined spacing of said bands. 5
18. In a machine of the class described, a plurality of rotary members, each member carrying means for clamping a bundle, means for rotating the members a single turn, means cooperating with each member for wrapping a band around the bundle, and means for uniting the ends of each of the bands near the completion of said rotation. 10
19. In a machine of the class described, a plurality of bundle supporting frames, each frame carrying means for clamping a bundle in tying location on the frame; means for rotating the frames simultaneously, means cooperating with each frame for wrapping a band around the bundle during said rotation, means for uniting the ends of each band before said rotation is completed, and means for releasing the bundle when it assumes its original position. 15
20. In a machine of the class described, a plurality of rotary members, each member carrying means for clamping a bundle, means for rotating the members a single turn, means for wrapping a band about the bundle during said rotation, means for adjusting the lateral spacing of said members, and means for uniting the ends of said band before the completion of the rotation. 20
21. In a machine of the class described, a plurality of rotary members, each member carrying means for clamping a bundle, means for rotating the members a single turn, means cooperating with each member for wrapping a band around the bundle during said rotation, means for uniting the ends of said bands near the completion of said rotation, means for releasing the bundle at the end of the rotation, and means for adjusting the lateral spacing of said members. 25
22. In a machine of the class described, a plurality of rotary members, each member carrying bundle clamping means, means for actuating the bundle clamping means simultaneously, and means for rotating the members simultaneously. 30
23. In a machine of the class described, a plurality of rotary members, each member carrying bundle clamping means, means whereby the interval between the members may be changed, means for actuating the bundle clamping means simultaneously, and means for rotating the members simultaneously. 35
24. In a machine of the class described, a plurality of rotary members, each member carrying bundle clamping means and bundle binding means, means whereby the bundle may be simultaneously wrapped with a plurality of bands spaced apart at adjustable intervals, means for actuating the bundle clamping means simultaneously, and means for rotating the members simultaneously. 40
25. In a machine of the class described, a plurality of rotary members, each member carrying bundle clamping means, means for actuating the bundle clamping means simultaneously, means for rotating the members simultaneously, means for wrapping a band about the bundle during said rotation, means for uniting the ends of said band before said rotation is completed, and means for releasing the bundle when it assumes its original position. 45
26. In a machine of the class described, a plu- 50

- 5 rality of rotary members, each member carrying means for clamping a bundle, means cooperating with each member for wrapping a band around the bundle, means for uniting the ends of each band, means for actuating the bundle clamping means simultaneously, and means for rotating the members simultaneously.
- 10 27. In a machine of the class described, a plurality of rotary members, means on each member for supporting and clamping a bundle, means whereby the members may be simultaneously rotated, and means for controlling the two previously mentioned means, said controlling means operating to cause first clamping of the bundle, then rotation of the bundle, and finally releasing of the bundle.
- 15 28. In a machine of the class described, a plurality of rotary members, means on each member for supporting and clamping the bundle, means for adjusting the lateral spacing of said members, means whereby the members may be simultaneously rotated, and means for controlling the bundle clamping and member rotating means, said controlling means operating to cause first 25 clamping of the bundle, then rotation of the bundle, and finally releasing of the bundle.
- 20 29. In a machine of the class described, a plurality of rotary members, means cooperating with each member for wrapping a band around the bundle, means for uniting the ends of each band, means on each member for supporting a bundle, means for clamping the bundle on the support, means whereby the members may be simultaneously rotated, and means for controlling the two 35 last-named means, said controlling means operating to cause first clamping of the bundle, then rotation of the bundle, and finally releasing of the bundle.
- 25 30. In a machine of the class described, a plurality of rotary members, means cooperating with each member for wrapping a band around a bundle, means for uniting the ends of each band, means whereby the intervals between said bands may be changed, means on each member for supporting and clamping a bundle, means whereby the chucks may be simultaneously rotated, and means for controlling the two last-named means, said controlling means operating to cause first 40 clamping of the bundle, then rotation of the bundle, and finally releasing of the bundle.
- 30 31. In a machine of the class described, means whereby a plurality of bundles may be rotated simultaneously about a common axis, and means for binding each of said bundles during said rotation.
- 35 32. In a machine of the class described, means whereby a plurality of bundles placed end to end may be clamped upon a support, means for rotating said bundles simultaneously and means for binding each of said bundles during said rotation.
- 40 33. In a machine of the class described, supporting and securing means for a plurality of bundles placed end to end, means whereby the secured bundles may be rotated simultaneously 45 each about a horizontal axis, and means for binding each of said bundles independently of the others during said rotation.
- 45 34. In a machine of the class described, means whereby a plurality of bundles placed end to end may be clamped simultaneously, means whereby the bundles may be rotated simultaneously about a common axis, means for binding each of said bundles independently of the others during said rotation, and means for releasing said bundles simultaneously.
- 50 35. In a machine of the class described, means whereby a plurality of bundles may be rotated simultaneously about a common axis, means for binding each of said bundles during said rotation with a plurality of bands, and means for adjusting the intervals between said bands. 5
- 55 36. In a machine of the class described, means whereby a plurality of bundles may be rotated simultaneously about a common horizontal axis, means for binding each of said bundles during 10 said rotation with a binding element, and means for maintaining said binding element under substantially constant tension.
- 60 37. In a machine of the class described, a plurality of rotary members, each member having 15 cooperating means for supporting and clamping a bundle, means for wrapping a band about a bundle, means for uniting the ends of said band, and means for maintaining the band under tension during the wrapping and end uniting operations. 20
- 65 38. In a machine of the class described, a plurality of rotary members, each member having 25 cooperating means for supporting and clamping a bundle, means for wrapping a band about the bundle, means for uniting the ends of said band, means for placing the band under a substantially constant tension during the wrapping operation, and means for adjusting the relative lateral positions of said members. 30
- 70 39. In a machine of the class described, a plurality of rotary members, each member having 35 cooperating means for supporting and clamping a bundle, means for rotating the clamped bundle, means for wrapping a band about the bundle during said rotation, means for uniting the ends of said band before the completion of said rotation, means for releasing the bundle when it assumes its original position, and means for placing the band under tension. 40
- 75 40. In a machine of the class described, a plurality of rotary members, each member having 45 cooperating means for supporting and clamping a bundle, means for rotating the clamped bundle, means for wrapping a band about the bundle during said rotation, means for placing the band under tension during said wrapping, and means for uniting the ends of the band. 50
- 80 41. In a machine of the class described, a plurality of rotary members, each member having 50 cooperating means for supporting and clamping a bundle, means for wrapping a band about the bundle, means for uniting the ends of said band before the completion of said rotation, means for placing the band under tension during the wrapping operation, means for releasing the bundle when it assumes its original position, and means for adjusting the spacing of said members. 55
- 85 42. In a machine of the class described, a plurality of rotary members including end chucks 60 and intermediate members all arranged to turn about a common horizontal axis, each of said members having cooperating means for supporting and clamping a bundle, the two end members being adapted to support the ends of bundles, the intermediate members supporting the bundle at any point, and each member having means for placing a band about the bundle during rotation. 65
- 90 43. In a machine of the class described, a member having cooperating means for supporting and clamping a bundle, means for actuating the bundle clamping means, means for rotating the member, means for wrapping a band about the bundle, means for uniting the ends of said band, 70
- 95 75

and means for compensating for slack in the band.

44. In a machine of the class described, a plurality of rotatable members, cooperating means on each member for supporting and clamping a bundle, means for controlling the rotation of the member and the bundle clamping means, said controlling means operating to cause first clamping of the bundle, then rotation of the bundle, and finally releasing of the bundle, means for wrapping a band about the bundle during rotation, means for uniting the ends of said band, and means for placing the band under tension during the wrapping operation.
45. In a machine of the class described, a plurality of rotary members, each member being provided with resilient bundle clamping means, and means for adjusting the lateral spacing of said members whereby bundles of various lengths may be accommodated.

46. In a machine of the class described, a plurality of rotary members, each member being provided with resilient clamping means for clamping a bundle, means for wrapping a band about the bundle during the rotation of said members, means for uniting the ends of said band before the completion of said rotation, and means for adjusting the lateral spacing of said members.

47. In a machine of the class described, a plurality of rotary members arranged to turn about a common axis, each of said members having cooperating means for supporting and clamping a bundle, the two end members being constructed and arranged to support the bundle end and each having means for placing a band about the bundle as it is rotated, the intermediate members each having means for placing a pair of bands about the bundle, and means for adjusting the relative positions of all the members.

48. In a machine of the class described, a plurality of rotary members arranged to turn about a common axis, each of said members having co-operating means for supporting and clamping the bundle, the end members each having means for placing a band under tension about the bundle as it is rotated, the intermediate members each having means for placing a pair of bands under tension about the bundle, one band on each side of the intermediate member.

49. In a machine of the class described, a plurality of rotary members, said members including a pair of end members and an intermediate member, each end member having means for holding the end of a bundle, the intermediate member having a bundle receiving opening and means whereby either a bundle or an intermediate portion of a bundle or the juxtaposed ends of two bundles may be supported and held.

50. In a machine of the class described, a plurality of rotary members, said members including a pair of end members and an intermediate member, each end member having means for holding a bundle adjacent its end, the intermediate member having a bundle receiving opening and means whereby either a bundle or the intermediate portion of a bundle or the ends of two bundles may be held, and independently operating means adjacent to each end member for placing a band about the bundle as it is rotated, and means for uniting the ends of said band.

51. In a machine of the class described, a plurality of rotary members, said members including a pair of end members and an intermediate member, each end member having means for holding a bundle adjacent its end, and means for placing

a band about the bundle as it is rotated, the intermediate member having means whereby either the intermediate portion of a bundle or the ends of two bundles may be held, and means adjacent each intermediate member whereby a pair of bands may be wrapped about said bundle or bundles during rotation.

52. In a machine of the class described, a plurality of rotary members, said members including a pair of end members and an intermediate member, each end member, having means for holding the end of a bundle, the intermediate member having a bundle receiving opening and means whereby either a bundle or the intermediate portion of a bundle or the ends of two bundles may be held, and means for independently adjusting the positions of one end member and the intermediate member.

53. In a machine of the class described, a plurality of rotary members, said members including a pair of end members and an intermediate member, each end member having means for holding the end of a bundle, the intermediate member having a bundle receiving opening and means whereby either a bundle or an intermediate portion of a bundle or the ends of two bundles may be held, means whereby the positions of the end members relative to each other and of the intermediate member relative to either end member may be adjusted, and means on each member for wrapping a band about the said bundle or bundles, and means for uniting the respective ends of said bands when said bundle or bundles are rotated.

54. In a machine of the class described, means for supporting a bundle, means for rotating the bundle, and an operating lever, and mechanism whereby when said lever is moved into one position it causes clamping of the bundle on its support and when moved into a second position it causes the rotation of the bundle while clamped.

55. In a machine of the class described, means for supporting a bundle, means for rotating a bundle, and an operating lever, and mechanism controlled by the lever so that when said lever is moved into a certain position, a clamping of the bundle on its support is effected, and when the lever is moved into a second position, rotation of the clamped bundle is effected, and when the lever is returned to its first position it causes cessation of the rotation and releasing of the bundle.

56. In a machine of the class described, means for rotatably supporting a bundle, means for clamping the bundle upon said supporting means, and a lever for controlling the clamping and the rotation of said bundle, said lever having a lost motion connection with the means for rotating, whereby the lever causes clamping of the bundle prior to the rotation thereof and releases the bundle only after rotation has ceased.

57. In a machine of the class described, a base, a pair of rotary members mounted on the base to rotate in vertical planes, one of said members being fixed relative to the base, the other member being adjustable toward and from the fixed member, and means on each member for holding the end of a bundle.

58. In a machine of the class described, a base, a pair of rotary members mounted on the base to rotate in vertical planes, one of said members being fixed upon the base, the other member being adjustable toward and from the fixed member, an intermediate member adjustable toward

- either end member, and means on each member for holding a bundle.
59. In a machine of the class described, a base, a pair of rotary members mounted on the base to rotate in vertical planes, one of said members being fixed upon the base, the other member being adjustable toward and from the fixed member, an intermediate member having a bundle receiving opening, and means on each member for supporting a bundle and means for clamping a bundle.
60. In a machine of the class described, a base, a plurality of rotary members mounted on the base to rotate in vertical planes, said members including end members and an intermediate member, each of said members having means for holding a bundle, the intermediate member being so made that the bundle may be moved relative to the member in two horizontal directions substantially at right angles to each other.
61. In a machine of the class described, a base, a rotary member mounted on said base, said member having a bundle receiving opening so made as to receive a bundle in such a way that the bundle may be moved relative to the member in two directions substantially at right angles to each other.
62. In a machine of the class described, a base, a plurality of open-mouthed bundle holding frames relatively adjustable on the base, each frame having bundle-clamping means cooperating therewith.
63. In a machine of the class described, a base, a plurality of open-mouthed bundle holding frames relatively adjustable on the base, each frame having bundle-clamping means and bundle-binding means cooperating therewith.
64. In a machine of the class described, a base, a plurality of open-mouthed bundle holding frames relatively adjustable on the base, each frame having bundle clamping means, bundle-binding means, and binder tensioning means cooperating therewith.
65. In a machine of the class described, a base, a plurality of open-mouthed bundle holding frames relatively adjustable on the base, each frame having bundle clamping means cooperating therewith, and means to rotate all of said frames simultaneously about a common axis.
66. In a machine of the class described a base, a plurality of open-mouthed bundle holding frames relatively adjustable on the base, each frame having bundle clamping means cooperating therewith, and means whereby said clamping means are actuated simultaneously on all the frames.
67. In a machine of the class described, a base, a plurality of open-mouthed bundle holding frames relatively adjustable on the base, each frame having bundle clamping means on each side thereof, and means whereby the clamping means are simultaneously actuated to clamp and release the bundle.
68. In a machine of the class described, a base, a plurality of open-mouthed bundle holding frames relatively adjustable on the base, means for simultaneously rotating all the frames, and means for simultaneously clamping a bundle upon said frames.
69. In a machine of the class described, a plurality of rotary bundle receiving frames, each of said frames having means for supporting a bundle whereby a bundle is receivable sidewise on the frames, means for binding the bundle with a band during rotation of the bundle by the frames, said bundle thereafter being removable from the machine sidewise in the same direction as it was placed on the machine.
70. In a machine of the class described, a base, a plurality of rotary frames mounted on the base, said frames having bundle receiving openings and means for clamping a bundle whereby the bundle may extend beyond the frame on either side of the frame, and means cooperating with each frame whereby a band may be placed about said bundle at any desired distance from either of the ends of said bundle.
71. In a machine of the class described, a rotary member, means on the member for holding the end of a band, means for rotating the member whereby the band is wrapped about the bundle, means for uniting the ends of said band before the rotation is completed, and means for tensioning said band.
72. A machine of the class described comprising, in combination, a plurality of rotatable bundle holding frames constructed and arranged to hold two or more bundles at one time; and means cooperating with said rotatable bundle frames for simultaneously and independently binding the two or more bundles aforesaid.
73. A machine of the class described comprising, in combination, a plurality of rotatable bundle holding frames constructed and arranged to hold two or more differently dimensioned bundles at one time; and means cooperating with each of said frames for simultaneously and independently binding the two or more bundles aforesaid.
74. In a machine of the class described, a plurality of rotary members, said members carrying bundle clamping means, means whereby a plurality of bundles of differing dimensions may be bound simultaneously upon rotation of the members, each bundle being clamped during said binding by different members.
75. In a machine of the class described, a rotary member, binding means cooperating with said member, bundle holding means provided on the member, and knotting mechanism mounted on said member, said bundle holding means being adjustable to hold the bundle with one corner adjacent the knotting mechanism.
76. In a machine of the class described, a rotary member, bundle holding means provided on the member, binding means cooperating with said member, and a tie-forming mechanism mounted on the member, said bundle holding means being adjustable to hold the bundle adjacent the tie-forming mechanism, whereby the binding means has its ends united against the bundle regardless of the size of the bundle.
77. In a machine of the class described, a rotary member, a knotting mechanism carried by said member, a binder carrier and binder tensioning means mounted below the member, said tensioning means including a tensioning wheel, said knotting mechanism being in alignment with said tensioning wheel in all positions of the rotary member.
78. A machine of the class described comprising, in combination, means for rotating a bundle, means for holding the end of a binder initially below the lower face of the bundle, means for holding a supply of the binder below the bundle, and means for retarding the feed of the binder; the parts being constructed and arranged so that

upon rotation of the bundle, the binder will be wrapped completely around it.

79. In a machine of the class described, a rotary member, a standard for supporting said member, a knotter head mounted on the member and adapted to hold one end of a binder, bundle supporting means mounted on said member, and means mounted on said standard for holding a binder so that the binder lies at an acute angle

5 10 to the bundle when the same is in its initial position, and when the bundle has been rotated more than three quarters of a revolution the binder will be wrapped entirely around the bundle and engaged by said knotter head.

15 80. In a machine of the class described, the combination with a rotary bundle supporting frame and a binder tensioning device cooperating with said frame, of a knotter mechanism, and means adjacent said mechanism for holding one 20 end of a binder during rotation of said frame, said binder extending in a line which is overlapped before the completion of said rotation, said knotter mechanism engaging the wire at such overlapping point.

25 81. In a machine of the class described, the combination with a rotary bundle supporting frame, a binder tensioning device cooperating with said frame and a knotter mechanism having means which securely holds one end of the 30 binder during the rotation of said frame, said knotter mechanism revolving with the frame and engaging the binder at the point where the binder overlaps itself, said knotter mechanism forming its knot after the overlapping of the binder has 35 taken place and before the rotation is completed.

82. In a machine of the class described, a rotary bundle supporting frame, said frame carrying a knotter head, said knotter head having a slot for receiving the binder, and means for guiding said 40 binder whereby as the frame is rotated the knotter head meets the binder in its course and encloses it in the slot, and means causing the knotter head to complete the operations of knotting the wire before the frame resumes its normal position.

45 83. A machine of the class described comprising, in combination, a support; a plurality of rolls mounted on said support; a rotary bundle holding frame carried by said rolls mounted on the support; means on the support for rotating the frame; said frame having an opening extending to its periphery to receive a bundle either laterally or longitudinally; and said rollers being so spaced apart that the frame is in constant engagement with at least three of said rollers so that the 50 rollers adequately guide and support the frame.

55 84. In a machine of the class described, a standard, rollers mounted on the standard, an open-mouthed rotary bundle receiving frame supported upon the standard by said rollers, a drive shaft, and means connected with the drive shaft for rotating in the same direction a pair of gears spaced apart from each other, said frame having gear teeth, said frame gear having a break at its periphery where the open mouth of the frame is provided, the power driven gears being spaced apart a distance greater than the width of the open mouth whereby one of said gears is always in mesh with the frame gear.

60 85. A machine of the class described comprising, in combination, a standard; a bundle receiving frame rotatably supported upon the standard; said frame having gear teeth by which it may be driven and an opening for receiving the bundle into tying location on the frame, the opening of the chuck causing a break in the periphery of said

frame; a plurality of rollers on the standard engaging with the frame to guide and support it; a pair of drive gears spaced apart from each other a distance greater than the width of the opening of the frame, and each engaging the frame gear, so that one of the drive gears is at all times in mesh with the frame gear; and said rollers being so spaced that at least three of the rollers at all times support and guide the frame.

65 86. A machine of the class described comprising, in combination, a rotary member having an open mouth to receive a bundle sidewise; said member carrying a clamping jaw, a rest for the bundle, and a knotter mechanism, and an abutment for positioning the bundle in tying location 10 relative to the knotter mechanism.

87. In a machine of the class described, means for rotating a bundle, means for holding the bundle thereon, said holding means comprising a fixed jaw providing a rest, an adjustable jaw movable longitudinally of the rest, and a clamping jaw movable laterally of the rest.

90 88. In a machine of the class described, means for rotating a bundle, means for holding the bundle thereon, said holding means comprising a fixed jaw providing a rest, an adjustable jaw 20 at right angles to the fixed jaw and movable longitudinally thereof, and a clamping jaw movable toward and from the fixed jaw.

89. In a machine of the class described, means for rotating a bundle, and means holding the bundle thereon, said holding means comprising a fixed jaw providing a rest, an adjustable jaw movable longitudinally of the rest, and a spring actuated clamping jaw movable toward and from 35 the rest.

90. In a machine of the class described, means for rotating a bundle, means for holding the bundle on the bundle rotating means, means for wrapping a band about the bundle during said 40 rotation, and means for uniting the ends of said band, the holding means comprising a fixed jaw providing a rest and a clamping jaw movable toward and from the rest.

91. In a machine of the class described, supporting means for a bundle comprising a rotary member, a fixed jaw on the member providing a rest, a clamping jaw movable relatively to the fixed jaw, an arm fixed to the clamping jaw, and means interposed in the path of said arm whereby the clamping jaw is moved away from the 50 fixed jaw substantially at the completion of the revolution of the member.

92. In a machine of the class described, a rotary bundle holding frame, a support therefor, 55 bundle clamping means mounted on the frame, and means mounted on said support and movable into and out of the path of part of the bundle clamping means to release or hold active said means.

93. In a machine of the class described, a rotary bundle holding frame, a support therefor, bundle clamping means mounted on the frame, means mounted on said support and movable into or out of the path of the bundle clamping means 60 to release or hold active said means, and means normally urging the movable means to move out of said path.

94. In a machine of the class described, a rotary bundle holding frame, a support therefor, 70 bundle clamping means including a movable jaw mounted on said frame, said jaw having an arm attached thereto, means for urging said jaw into clamping position with said arm extended beyond the periphery of said frame, and an engagement 75

- arm mounted on said support and movable into or out of the path of the end of said arm to release or hold active the movable jaw.
95. In a machine of the class described, a bundle supporting frame, an abutment adjustable relative to the frame, means for holding said abutment at selected points of adjustment, a bar slidably mounted on said frame, a clamping jaw carried by said bar, means for urging said jaw into clamping position, and means for restraining said movement of said jaw.
96. In a machine of the class described, a bundle supporting frame, an abutment adjustable relative to the frame, means for holding said abutment at selected points of adjustment, a plurality of rods slidably mounted on said frame, a clamping jaw carried by said rods, means for actuating said rods for urging said jaw into clamping position, and means for restraining such movement of said jaw.
97. A machine of the class described comprising, in combination, a gear having a bundle passageway therethrough, a bundle support carried on said gear, an abutment against which to position a bundle on said support, wire knotter means, wire tension means, means for rotating the gear a single turn at a time, means cooperating with the gear for placing the band about the bundle, and means for actuating the wire knotter means to secure the band in position about the bundle.
98. A machine of the class described comprising, in combination, a gear having a bundle passageway therethrough and providing a bundle support; means for rotating the gear to rotate a bundle supported thereby; means for holding the end of a binder below the lower face of the bundle in the initial position of the gear; and means for tying the binder after the bundle is enveloped thereby.
99. In a machine of the class described, a reel, a support upon which the reel is rotatably mounted, a tension arm carried by said support, a friction disk interposed between the tension arm and the reel, a second friction disk mounted on said support and bearing against the other face of said reel, resilient means mounted upon said support and bearing against the second-named friction disk whereby both friction disks engage with said reel, and means for regulating the pressure of said resilient means.
100. In a machine of the class described, a reel, a support, means for restraining free rotation of the reel, a frame on the support, a tension wheel on said frame, said tension wheel having a binding element encircled therearound for the convex tensioning thereof and means for restraining free rotation of said wheel.
101. In a machine of the class described, a reel, a support upon which the reel is rotatably mounted, means mounted on said support for restraining free rotation of the reel, a frame mounted on the support, a tension wheel on said frame, said tension wheel having a binding element encircled therearound for the convex tensioning thereof, friction disks bearing against each side of the tension wheel, and adjustable means for varying the pressure of the friction disks upon said tension wheel.
102. In a machine of the class described, a reel, means for supporting the reel, friction disks mounted on the reel support and bearing against each side of the reel, means for varying the pressure of said friction disks, a frame mounted on the support, a tension wheel provided at the other end of said frame, friction disks bearing against the sides of said tension wheel, and means for adjusting the pressure of the tension wheel friction disks.
103. In a machine of the class described, a support, a bundle supporting frame rotatable upon said support, means on the frame for uniting the ends of a band, and means on the support for engaging with a portion of the first-named means when the frame is rotated to actuate the band end uniting means.
104. In a machine of the class described, a support, a bundle holding frame rotatable upon said support, a spider rotatably mounted on said frame, means on the support for causing partial rotation of said spider when the frame is rotated, and means actuated by movement of the spider for uniting the ends of a band.
105. A machine of the class described comprising, in combination, a support; a bundle supporting frame rotatable upon said support; means for holding a wire band in position to be engaged by the bundle when rotated for envelopment of the bundle; a spider rotatably carried by the frame; means mounted upon the support and arranged for engagement with one arm of the spider to cause partial rotation thereof after the bundle is enveloped by the band; and tying mechanism actuated by the spider when partially rotated for uniting the ends of the band.
106. A machine of the class described comprising, in combination, a rotary bundle holding frame; wire tying means carried on said rotary frame; wire carrying means secured adjacent the frame; and means fixed relative to said rotary support for actuating the wire tying means.
107. In a machine of the class described, a wire twisting head, and means for actuating said head, said means including actuating means for rotating said head, and means for moving the head longitudinally after one revolution has taken place, said longitudinal movement being carried out while the head is being rotated.
108. In a machine of the class described, a knotter head, and means for actuating said head, said actuating means including means for rotating the head, also means for moving the head longitudinally during the course of its rotation, and means for resisting the longitudinal movement of said head.
109. In a machine of the class described, a rotary bundle holding frame carrying knotter means, said means including a bevelled gear, means for rotating said bevel gear during each rotation of said frame, a knotter head rotated by the bevel gear, means operated by the rotation of the bevel gear for moving the knotter head longitudinally, and means for engaging with and guiding a band into said knotter head as the chuck is rotated.
110. In a machine of the class described, a knotter mechanism including a rotary knotter head, a gear secured to said head intermediate its ends, a gear meshing with the knotter head gear to rotate the head and having wider teeth than said knotter head gear, a band-receiving slot running longitudinally of the head, a bore in one end of the head for receiving the end of a band, and means for moving the head longitudinally with the two gears maintained in mesh.
111. In a machine of the class described, a rotary bundle holding frame, a knotter head mounted on the frame, a slot running longitudinally of the knotter head, a bore in one end of said head for receiving the end of a band, and a roller mounted on the knotter head for engaging

ing with the band during the course of rotation of said frame to guide the band into said slot.

112. In a machine of the class described, a rotary bundle supporting frame carrying a knotter mechanism, said knotter mechanism including a slideable frame, springs for restraining movement of the frame in one direction, a band-engaging roller fixed upon the frame, means for moving said frame against the resistance of said springs when the knotting mechanism is actuated, and means provided by the knotter mechanism and cooperating with said roller for engaging with said band before the completion of the rotation of said frame.

113. In a machine of the class described, a rotary bundle holding means, a knotting mechanism carried by said means, band-engaging means cooperating with said knotting mechanism for guiding said band into said knotting mechanism at a certain point in the rotation of said means, a support for the rotary means, a frame mounted on said support, a tension wheel supported on said frame said wheel being adapted to convexly tension said band, a band guide mounted on the frame below said tension wheel, means for holding a supply of the band, said band passing from said means through the band guide to the tension wheel, the band passing once around the tension wheel and then to the knotting mechanism and having its end there held, the band guide acting to hold the band on the tension wheel in such position that it will always lead off to the knotting mechanism in a true line whereby the convexly tensioned band will lie flat against the periphery of the bundle and a portion thereof will be engaged by said engagement means.

114. In a machine of the class described, a rotary knotter head, means in said head for receiving and holding the end of a band, and a tensioning device for the band, a length of the band being extended between the knotter head and the tensioning device with the angle between the band length and the band end less than a right angle, whereby the end of the band is held in the knotter head.

115. In a machine of the class described, a drive shaft, power means for turning said shaft, rotatable means for supporting an article, means interposed between said supporting means and the drive shaft whereby the supporting means is rotated once on its axis at a time, and means for wrapping a band about the article during said rotation.

116. In a machine of the class described, means whereby a plurality of bundles may be rotated simultaneously about a common axis, means for placing a band about each bundle as it is rotated, and means for compensating for the variation in tension of each band brought about by the rotation of the bundles.

117. In a machine of the class described, means whereby a plurality of bundles placed end to end may be rotated simultaneously, means for binding each of said bundles during said rotation with a band, means for tensioning each individual band, and means connected with the tensioning means for moving the same to take up slack in the bands brought about by the rotation of the bundles.

118. In a machine of the class described, means whereby a plurality of bundles placed end to end may be clamped simultaneously, means whereby the bundles may be rotated simultaneously about a common horizontal axis, means for binding each

of said bundles during said rotation, and means for compensating for variation in tension in said binders caused by the rotation of the bundles.

119. In a machine of the class described, means whereby a plurality of bundles placed end to end may be clamped, means whereby the clamped bundles may be rotated simultaneously about a common axis, means for binding each of said bundles during said rotation, means for adjusting the spacing of said binding means, means for tensioning the binders, and means for compensating for the variation in tension caused by the rotation of the bundles.

120. In a machine of the class described, a plurality of rotary members mounted to turn about a common horizontal axis, each of said members having cooperating means for supporting and clamping a bundle, the two end members being adapted to support the bundle ends, the intermediate members having open mouths to receive the bundle, each member having cooperating therewith means for placing a band about the bundle, means for tensioning each band, and means for preventing slack in said bands during rotation of the bundle.

121. In a machine of the class described, a plurality of rotary bundle supporting members, said members comprising a pair of end members and an intermediate member, each end member having cooperating means for supporting and holding the end of a bundle, the intermediate member having means whereby either the intermediate portion of a bundle or the ends of two bundles may be supported and held, means cooperating with each member for placing a band about the bundle, and independent means acting upon each band to maintain automatically the tension of the band regardless of the size of the bundle.

122. In a machine of the class described, means for holding the end of a wire below the lower face of a bundle, means for rotating the bundle so that the wire is wrapped about the bundle, means for uniting the held wire end with the wire, and means for severing the wire beyond the tie.

123. In a machine of the class described, means for holding a wire near a bundle with the wire end bent to form a kink, means for supporting a bundle with said kink held adjacent the lower face of the bundle, means for wrapping the wire about the bundle, means for uniting the wire to said wire end, and means for severing the wire.

124. In a machine of the class described, means for holding the end of a wire with said end bent with respect to the rest of the wire, means for rotating a bundle to effect wrapping of the wire about the bundle, means for twisting the wire to form a twist tie, and means for severing the wire after uniting.

125. In a machine of the class described, means for holding an end of a wire with said end bent to form a kink held adjacent the lower face of a bundle, means for rotating the bundle to wrap the wire about it with the wire returned alongside the held end, means for uniting that portion of the wire so returned with the held end, and means for severing the wire beyond the tie.

126. In a machine of the class described, means for securely holding the end of a wire, said means forming a kink in said wire near its end and holding the kinked end adjacent the lower face of a bundle, means for rotating a bundle and the wire end holding means to enclose the bundle with the wire, means for uniting the held wire

end to the wire, and means for severing the wire beyond the tie.

127. In a machine of the class described, means for holding an end of a wire, means for encompassing a bundle with the wire, and means for uniting the wire with the held end, said wire uniting means forcibly pulling the wire end out of the holding means as the tie is formed.

128. A machine of the class described comprising, in combination, a gear having a passageway for entry of the object to be bound; spaced bundle supporting elements; spaced abutment elements for positioning the object on said supports; means for rotating the gear; means for convexly tensioning and wrapping a band about the object during said rotation; means for tensioning the band; wire tying means disposed below the support in the path of movement of the wire; and means for actuating the wire tying means to secure the wire to the object.

129. In a machine of the class described, means for supporting a bundle, means for rotating the supporting means, means whereby as the bundle is rotated a wire is wrapped around the same, and means for tying the wire during said rotation, with the tie formed to lie substantially in the plane of one of the bundle faces.

130. In a machine of the class described, a pair of rotary frames arranged to turn about a common horizontal axis, said frames being adapted to support the bundle ends, means for clamping the bundle ends, means for wrapping a band about the bundle during the rotation of the frames, means for uniting the ends of said band before the completion of said rotation, and means for releasing said bundle when it assumes its original position.

131. In a machine of the class described, a rotary bundle holding frame, means on the frame for holding the end of a band, means for rotating the frame whereby the band is wrapped about the bundle, means for convexly tensioning the band so that the convex tension of the band will cause the band to lie flat against the periphery of the bundle, and means operable to prevent slack occurring in the band during the rotation of the bundle, said means being operable synchronously with the rotation of the chuck.

132. A machine of the class described comprising, in combination, means for holding a supply of wire; means for restraining withdrawal of the wire therefrom; means for tying the wire; means frictionally retarded for convexly tensioning and guiding the wire into the tying means; and means for mechanically moving the wire guiding means to prevent any tendency in the wire to lose its tension when the wire is wrapped around a bundle.

133. A machine of the class described comprising, in combination, a plurality of rotary bundle receiving frames each having bundle supporting and clamping means; one of said frames being intermediate the others and so constructed and arranged that it may support and clamp either a single bundle or an intermediate part of a bundle or the juxtaposed ends of two bundles; and means for changing the position of said intermediate frame relative to the other two aforementioned to accommodate various lengths of bundles.

134. A machine of the class described comprising, in combination, a bundle holding frame constructed and arranged to revolve under the control of an operator; bundle clamping means on said frame cooperating with a relatively fixed rest, said clamping means accommodating bundles of various heights; an adjustable abutment

member extending between the clamping member and said rest to aid in the positioning of bundles of various widths; said frame being open axially to accommodate bundles of any length.

135. A machine of the class described comprising, in combination, a rotary bundle carrier; means for rotating the carrier; said carrier having an opening extending from its perimeter inwardly and of sufficient dimensions to accommodate bundles of the size for which the machine is designed, said bundles being insertable either in the direction of the axis about which the carrier turns or in the direction in which the opening extends; and bundle clamping means on the carrier bordering said opening.

136. A machine of the class described comprising, in combination, a rotary bundle carrier; wire tying mechanism supported on said carrier and revolving therewith; means restraining feeding of the wire to the tying mechanism; means guiding and supporting the wire in position to be engaged by the bundle and to be drawn out under tension as the bundle is rotated by its carrier, so that the bundle is enveloped by the wire during each rotation of the carrier, and so that the wire is fed into the tying mechanism when the bundle is rotated; and mechanism including a control lever for effecting a single rotation of said carrier following each actuation of the lever.

137. A machine of the class described comprising, in combination, a rotary bundle carrier; a wire tying mechanism supported on said carrier and revolving therewith, said tying mechanism including wire gripping means; means restraining feeding of the wire to the tying mechanism; and means for convexly tensioning and guiding and supporting the wire in position to be engaged by the bundle and to be drawn out under tension as the bundle is rotated by its carrier, so that the bundle is enveloped by the convexly tensioned wire during each rotation of the carrier, and so that the wire, when so wrapped, lies flat and tightly against the periphery of the bundle and is laid in the tying mechanism.

138. A machine of the class described comprising, in combination, a rotary bundle carrier; a wire tying mechanism supported on said carrier and revolving therewith, said tying mechanism including wire gripping means; means restraining feeding of the wire to the tying mechanism; means guiding and supporting the wire in position to be engaged by the bundle and drawn out under tension as the bundle is rotated by its carrier, so that the bundle is enveloped by the wire during each rotation of the carrier, and so that the wire is laid in the tying mechanism when so wrapped; and means movable to prevent lessening of wire tension caused by engagement during rotation of a small bundle secured eccentrically relative to the axis of rotation of said carrier.

139. In a machine for banding bundles, an adjustable abutment against which to locate a bundle on the support, means for holding said abutment at a selected point of adjustment, a bundle support; spring actuated clamping means movable relative to the support and adapted for engaging and clamping the bundle so located on the support; and a cam element operative for effecting release of the clamping means from the bundle.

140. In a machine for banding bundles, a support, an adjustable abutment against which to locate a bundle on the support, means for holding said abutment at a selected point of adjustment, bundle clamping means including a guide

bar; a clamping bar adjustably secured to the guide bar; and a spring arranged and adapted for actuating the guide bar to effect the clamping of the bundle by the clamping bar.

5 141. In a machine for banding bundles, a support, an adjustable abutment against which to locate a bundle on the support, means for holding said abutment at a selected point of adjustment, bundle clamping means including a guide 10 bar, a clamping bar adjustably secured to the guide bar; a spring arranged and adapted for actuating the guide bar to effect the clamping of the located bundle; a roller associated with the guide bar; and an element adapted for actuating 15 the roller to lift the clamping bar for releasing the bundle.

142. A machine for banding bundles, comprising in combination, a bundle support; an adjustable abutment against which to locate a bundle on 20 the support; means movable relative to the support adapted to compensatingly clamp the bundle located on the support; a spring arranged and adapted for actuating said clamping means; and means for lifting the clamp against the tension of 25 the spring to release the bundle and return the clamp to normal position preparatory to the receiving of the next bundle.

143. A machine for banding bundles, comprising in combination, a frame; a bundle support; 30 wire tying means in fixed position below the support; abutment means adjustable toward and from the tying means for locating a bundle in position to be bound and tied; means for enclosing the located bundle with a band; means on 35 the frame for tensioning the band during the binding of the bundle; wire take-up means on the frame; spring actuated means movable relative to the support for adjustably clamping the bundle on the support; and means for lifting the clamp 40 to release the bound bundle.

144. A machine for banding bundles, comprising in combination, means for supporting and means for registering a bundle arranged and adapted to receive a bundle directly into banding 45 position; the means for registering the bundle being adjustable relative to said supporting means; means movable at right angles to said registering means for compensatingly clamping a bundle; means for enclosing the bundle with a 50 band; means for actuating the clamping means and means for lifting the clamp to release the bundle and arrange the clamp preparatory to the clamping of the next bundle.

145. In a bundle tying machine, means for 55 supporting a bundle, bundle abutment means adjustable relative to said supporting means, a presser foot arranged above the bundle supporting means, a spring tending to depress said foot, and means for moving the foot in opposition to 60 the spring.

146. In a bundle banding machine, means for 65 supporting a bundle; an abutment adjustable relative to said supporting means for locating a bundle in proper position to be bound; a sliding clamp bar; a bundle clamp adjustable relative to said bar; means for adjustably securing the clamp to the bar; a bracket connected to the bar; and a spring connected to the bracket adapted 70 for actuating the bar and clamp for effecting pressure holding of the bundle in said banding position on the support.

147. In a bundle banding machine, means for 75 supporting a bundle; an abutment adjustable relative to said supporting means for locating a bundle in proper position to be bound; a sliding

clamp bar; a bundle clamp adjustable relative to said bar; means for adjustably securing the clamp to the bar; a bracket connected to the bar; a spring connected to the bracket adapted for actuating the bar and clamp for effecting pressure holding of the bundle in said banding position on the support; and means adapted to elevate the clamp to release the bundle. 5

148. In a bundle banding machine, means for supporting a bundle; an abutment adjustable relative to said supporting means for locating a bundle in proper position to be bound; means for adjustably securing said abutment at a selected point; a sliding clamp bar; a bundle clamp adjustable relative to said bar; means for adjustably securing the clamp to the bar; a bracket connected to the bar; a pressure spring connected to the bracket adapted for actuating the bar and clamp for effecting pressure holding of the bundle in said banding position on the support; and means adapted to elevate the clamp and bar against the pressure of the spring including a roller and a cam shaped element adapted to elevate the roller whereby the bundle is released and the clamp maintained in elevated position to provide for the placing of the next bundle to be banded. 10 15 20 25

149. In a bundle binding machine, means for supporting a bundle, an abutment adjustable relative to said supporting means for locating a bundle in proper position to be bound, means for adjustably securing said abutment at a selected point, a clamp movable relative to the bundle adapted for engaging and holding a bundle in said binding position on the support; means 30 for actuating the clamp including a spring adapted to compensatingly effect pressure holding of the bundle in one direction of movement of the clamp and a cam and roller adapted to move the clamp 35 in the opposite direction to release the bundle. 40

150. In a bundle binding and tying machine, means for supporting a bundle, wire tying means in a fixed position below the support including a rotary twister, an abutment movable toward and from said twister for locating the bundle in proper tying position on the supporting means, means for adjustably securing said abutment at a selected point, a clamp movable relative to the bundle adapted for engaging and holding a bundle in said position on the support and means 50 for actuating the clamp including a spring adapted to compensatingly effect pressure holding of the bundle in one direction of movement of the clamp and a cam and roller adapted to move the clamp in the opposite direction to release the bundle. 55

151. In a bundle binding and tying machine, means for supporting a bundle, wire tying means; means adjustable toward and from the wire tying means adapted and arranged to receive the 60 bundle directly into binding and tying position on the support; a clamp movable relative to the bundle adapted for engaging and holding a bundle as positioned in tying position of the support and means for actuating the clamp including a spring adapted to compensatingly effect pressure holding of the bundle in one direction of movement of the clamp and a cam and roller adapted 65 to move the clamp in the opposite direction to release the bundle. 70

152. In a bundle binding machine, a bundle support, an abutment adjustable along the support for locating the bundle directly in binding position on the support, means for effecting encircling 75 of a wire about the bundle and causing the wire

to lie flat against the sides thereof in a predetermined plane, comprising an oscillatory element, a tensioning wheel rotatably mounted on said element and around which the wire is encirclingly wound and drawn thereover for flexing the wire away from the bundle and in said plane, means for retarding the rotation of said wheel, and means for regulating the pressure of said retarding means to effect tight hugging of the flexed wire about the bundle.

153. In a bundle binding machine, means for supporting a bundle, means against which the bundle is placed directly into binding position on the support, means for effecting encircling of a wire about the bundle and causing the wire to lie flat against the sides thereof in a predetermined plane, comprising an oscillatory carrier, a tensioning wheel rotatably mounted on said oscillatory carrier and around which the wire is encirclingly wound and drawn thereover for flexing the wire away from the bundle and in said plane, means for retarding the rotation of said wheel, and means for regulating the pressure of said retarding means to effect tight hugging of the flexed wire about the bundle.

154. In a bundle binding machine, means for supporting a bundle, means against which the bundle is placed directly into binding position on the support, means for effecting encircling of a wire about the bundle and causing the wire to lie flat against the sides thereof in a predetermined plane, comprising a carrier, a tensioning wheel rotatably mounted on said carrier and around which the wire is encirclingly wound and drawn thereover for flexing the wire away from the bundle and in said plane, means for retarding the rotation of said wheel, and means for oscillating said carrier to effect tight hugging of the flexed and tensioned wire about the bundle.

155. In a bundle tying machine, means for clamping and holding a bundle comprising, in combination, a frame, a bundle support in fixed location on said frame, a jogger clamp, a slidable jogger bar connected with and supporting said jogger clamp, means for actuating the bar to cause the jogger clamp to strike the supported bundle a sharp blow, and means for restoring the jogger bar to its initial position and thereby releasing the jogger clamp from the bundle.

156. In a bundle tying machine, means for clamping and holding a bundle comprising, in combination, a frame, a bundle support in fixed location on said frame; an abutment against which to place a bundle on said support, a jogger clamp, a slidable jogger bar connected with and supporting said jogger clamp, means for quickly actuating the bar to cause the jogger clamp to strike the supported bundle a sharp blow, the clamp then holding the bundle, and means for restoring the jogger bar to its initial position and thereby releasing the jogger clamp from the bundle.

157. In a bundle tying machine, means for clamping and holding a bundle comprising, in combination, a frame, a bundle support in fixed location on said frame, an abutment against which to place a bundle on the support, a jogger clamp, a slidable bar connected with and supporting said jogger clamp, means for quickly actuating the bar to cause the jogger clamp to strike the supported bundle a sharp blow and to hold the bundle, the distance of movement of the jogger and bar being controlled by the size of the bundle, and means for restoring the jogger bar to its ini-

tial position and releasing the jogger clamp from the bundle.

158. In a bundle tying machine, in combination, means for supporting a bundle, an abutment against which the bundle is placed on the support; a jogger clamp; means for quickly actuating the clamp for striking the supported bundle a sharp blow and holding the same on the support; means for holding the end of the wire; a slotted rotary wire twister disposed adjacent said support; means for tensioning the wire; an oscillatory carrier; means mounted on said carrier for convexly tensioning and guiding the wire about the supported bundle and into the slot of the twister; means for oscillating the carrier to effect tight hugging of the convexly tensioned wire against the sides of the bundle; and means for rotating the twister to form a tie for securing the band about the bundle.

159. In a bundle tying machine, in combination, means for supporting a bundle, an abutment against which the bundle is placed on the support; a jogger clamp; means for quickly actuating the clamp for striking the supported bundle a sharp blow and holding the same on the support; means for holding the end of the wire; a slotted rotary wire twister disposed adjacent said support; means for tensioning the wire; an oscillatory carrier; means mounted on said carrier for convexly tensioning and guiding the wire about the supported bundle and into tying position within the slot of the twister; means for oscillating the carrier to effect tight hugging of the convexly tensioned wire against the sides of the bundle; means for rotating the twister to form a tie for securing the band about the bundle; and means for releasing the jogger clamp from the bundle.

160. In a bundle tying machine, a frame; a bundle support in fixed position on said frame; a knotted mechanism disposed in fixed position below the plane of the support; an abutment adjustable toward and from said mechanism for receiving bundles of different widths in fixed tying location on the support above said mechanism; a bundle clamp; an actuating bar connected to said clamp; and means for actuating the bar in such manner that the clamp is caused to engage and hold the located bundle irrespective of the size of the bundle, within the limits of actuation of the clamping bar.

161. In a bundle tying machine, a frame, a bundle support in fixed position on said frame; a knotted mechanism disposed in fixed position below the plane of the support; an abutment adjustable toward and from said mechanism and for receiving bundles of different widths directly into tying location with respect to said mechanism; a bundle clamp; a bar connected to said clamp; means for actuating the bar to cause the clamp to engage and hold the located bundle irrespective of the size of the bundle, within the limits of movement of the bar; and means for actuating the bar to cause the clamp to release the bundle.

162. In a bundle tying machine, a frame; a bundle support in fixed position on said frame; a knotted mechanism disposed in fixed location below the plane of said support; an abutment adjustable toward and from said mechanism for receiving bundles of different widths in fixed tying location on the support; a jogger clamp; a jogger bar connected with the clamp; means for quickly actuating the jogger bar to cause the clamp to strike the located bundle a sharp blow and to hold the same irrespective of the size of the bundle,

within the limits of movement of the jogger bar.

163. In a bundle tying machine, a frame; bundle supporting means fixed on the frame; a knotter mechanism disposed in fixed location 5 below the plane of said support; an abutment adjustably secured relative to said knotter mechanism against which a bundle is placed directly into predetermined tying location on the support above said mechanism; means for clamping the 10 bundle in said supported tying location; means for wrapping a tensioned wire into band formation about the located bundle; and means for actuating the knotter mechanism to intertwist portions of the wrapped wire to secure the band 15 about the bundle.

164. In a bundle tying machine, a frame; bundle supporting means fixed on the frame; a knotter mechanism disposed in fixed location below the plane of said support; an abutment adjustably secured relative to said knotter mechanism 20 against which a bundle is placed directly into predetermined tying location on the support above said mechanism; a jogger bundle holding clamp; a jogger bar connected to said clamp; means for quickly actuating the bar to cause the 25 jogger clamp to strike the supported bundle a sharp blow and to hold the bundle for the banding thereof; means for wrapping a tensioned wire into band formation about the located and 30 clamped bundle; and means for actuating the knotter mechanism to intertwist portions of the wrapped wire to secure the band in tensioned state about the periphery of the bundle.

165. In a binding machine, means for clamping 35 a binding wire, means for tensioning said wire, means for holding an object to be bound and tied comprising a support and an adjustable abutment, means for effecting encircling of the clamped and tensioned wire about the held object, 40 and means intermediate the clamping and the tensioning means for effecting tight hugging of the wire against the object.

166. In a binding machine, means for gripping 45 a binding wire, means for tensioning said wire, a support, an abutment adjustable relative to the support for positioning an object directly into binding position on the support, and means intermediate the gripping means and the tensioning means for effecting encircling of the gripped and 50 tensioned wire about the abutted object and flexing the wire to effect tight hugging of the wire about and against the sides of the object.

167. In a binding machine, means for gripping 55 a binding wire, means for tensioning said wire, a support, an abutment adjustable relative to the support for positioning an object directly into binding position on the support, means intermediate the gripping means and the tensioning means for effecting encircling of the gripped and 60 tensioned wire about the held object and flexing the wire to effect tight hugging of the wire about and against the sides of the object, and means for moving said latter means in opposite directions.

65 168. In a binding machine, means for gripping a binding wire, means for tensioning said wire, means for holding an object to be bound and tied comprising a support and an adjustable abutment, means intermediate the gripping means and the 70 tensioning means for effecting encircling of the gripped and tensioned wire about the held object and flexing the wire to effect tight hugging of the wire about and against the sides of the object, and means for oscillating said latter 75 means.

169. In a binding machine, means for supporting an object to be wrapped with wire, means for effecting wrapping of the wire about the object and in a predetermined plane, including a rotary element continuously contacting said wire for flexing it away from the object and in the plane of wrapping throughout the entire wrapping operation, and means for moving said latter means in opposite directions. 5

170. In a binding machine, means for supporting 10 an object to be wrapped with wire, means for effecting wrapping of the wire about the object and in a predetermined plane, including a rotary element continuously contacting said wire for flexing it away from the object and in the plane 15 of wrapping throughout the entire wrapping operation, and means for oscillating said latter means.

171. In a binding machine, means for supporting 20 an object to be wrapped with wire, means for gripping the wire, means for effecting wrapping of the wire about the object and in a predetermined plane, including a rotary element continuously contacting said wire for flexing it away from the object and in the plane of wrapping throughout the entire wrapping operation, means for retarding rotation of said rotary element, and 25 means for oscillating said latter means.

172. In a binding machine having a wire tying mechanism, means for supporting an object to 30 be wound with wire, an abutment adjustable relative to said tying mechanism and to the supporting means for locating the object thereon in proper binding position, a pressure foot arranged above the supporting means, a spring to depress the pressure foot to clamp the object on the supporting means, means for effecting winding of the wire about the object and in a predetermined plane, including means contacting said wire for flexing it away from the object and in the plane 40 of the winding throughout the entire winding operation and means for moving the pressure foot in opposition to the spring.

173. In a binding machine having a wire-tying mechanism, means for supporting an object to 45 be wound with wire, an abutment adjustable relative to said tying mechanism and to the supporting means for locating the object thereon in proper binding position, a pressure foot arranged above the supporting means, a spring to 50 depress the pressure foot to clamp the object on the supporting means, means for effecting winding of the wire about the object and in a predetermined plane, including means contacting said wire for flexing it away from the object and in the plane 55 of the winding throughout the entire winding operation, and means for moving said wire contacting means in opposite directions, and means for moving the pressure foot in opposition to the spring. 60

174. A jogger mechanism for bundling machines comprising the combination with a bundling machine of a table to support the bundle, an abutment against which the bundle is to be placed, a slidible jogger arm, slidible means for 65 the support of the arm, means to effect advance of the slidible means to cause the jogger bar to strike the bundle a sharp blow, means to thereupon disengage the jogger arm advancing mechanism therefrom, and means to engage the jogger 70 bar mechanism to retract said bar upon the completion of a tie.

175. A jogger mechanism for tying machines comprising the combination with a tying machine of a table for the support of a bundle to 75

be tied, a fixed abutment against which the bundle is also placed, a slideable jogger arm, slideable means supporting the jogger arm, means to advance and retract said jogger arm and to hold 5 the jogger arm advanced for a part of the time during the operation of the tying machine, and means to damp the action of said jogging mechanism.

176. A jogging mechanism for bundling machines comprising the combination with a bundling machine of a table for the support of the bundle, an abutment on the table against which the bundles are placed, a jogger arm, means to cause the jogger arm to advance to strike the 10 bundle a sharp blow and to resist the retraction of the jogger bar, and means to damp the action of the jogger arm.

177. A jogger mechanism for bundling machines comprising the combination with a bundling machine of a table to support the bundle, an abutment against which the bundle is to be placed, a slideable jogger arm, a bar for the support of the arm, means to advance the bar to cause the jogger bar to strike the bundle a sharp 25 blow and to retract the jogger bar, including means to disengage from the bar to permit the jogger arm to hold the bundle during the binding thereof, and to reengage the bar to retract said bar upon completion of a tie.

178. A jogger mechanism for bundling machines comprising the combination with a bundling machine of a table to support the bundle, an abutment against which the bundle is to be placed, a slideable jogger arm, a bar for the support 30 of the arm, means to advance the bar to cause the jogger bar to strike the bundle a sharp blow, means to engage the jogger bar mechanism to retract said bar upon the completion of a tie, and means to engage and disengage with the 35 jogger bar mechanism for alternately clamping and releasing the bundle.

179. In a binding machine, means for supporting an object to be bound with wire, an abutment adjustable relative to the supporting means 45 for locating the object thereon in proper binding position, a pressure foot arranged above the supporting means, a spring to depress the pressure foot to clamp the object on the supporting means, means for clamping the binding wire, means for tensioning said wire, means for effecting wrapping of the clamped and tensioned wire about an object to be bound, including a rotary 50 wire guide for wrapping the wire tightly against three sides of the object and into band formation thereabout, said guide flexing the wire for effecting tight hugging of the wire against the object.

180. In a binding machine, means for supporting an object to be bound with wire, an abutment adjustable relative to the supporting means for locating the object thereon in proper binding position, a pressure foot arranged above the supporting means, a spring to depress the pressure foot to clamp the object on the supporting 60 means, means for clamping the binding wire, means for tensioning the wire, means including a rotatable element for effecting wrapping of the clamped and tensioned wire about an object, means including a wire lead-off member intermediate the clamping and the tensioning means for wrapping the wire tightly against three sides of the object and into band formation thereabout, said lead-off member flexing the wire for effecting tight hugging of the wire against the 65

object, and means for actuating said wrapping means consisting solely of members fixed against lateral shifting movement.

181. In a binding machine, means for supporting an object to be bound with wire, an abutment adjustable relative to the wire clamping means and to the supporting means for locating the object thereon in proper binding position, a pressure foot arranged above the supporting means, a spring to depress the pressure foot to 10 clamp the object on the supporting means, means for clamping the binding wire, means for tensioning the wire, and wire guide means for effecting wrapping of the tensioned wire about an object to be bound, said guide means being positioned to contact the wire so as to flex the wire away from the object and in the plane of wrapping. 15

182. In a binding machine, means for clamping the binding wire, means for supporting an 20 object to be bound with wire, an abutment adjustable relative to the wire clamping means and to the supporting means for locating the object thereon in proper binding position, a pressure foot arranged above the supporting means, a 25 spring to depress the pressure foot to clamp the object on the supporting means, means for tensioning the wire, and wire guide means for effecting wrapping of the wire about an object to be bound, said guide means being positioned to contact the wire so as to flex the wire away from the object and in the plane of the wrapping of the object, and means for moving the guide means in opposite directions.

183. In a bundle-tying machine the combination of oscillatory means to wrap a tie wire around a bundle, a wheel which the tie wire encircles to bend it so that it will be convex, a cutter for severing the tie wire, and means to secure the tie ends together. 35

184. In a bundle-tying machine, the combination of a support, means to secure a bundle thereon, an oscillatory wire placing means, means carried by said oscillatory wire placing means to curve the tie wire while placing the same around 45 the bundle, and tie wire cutting and twisting means operatively mounted in the machine and positioned to receive the wire carried by said wire placing means, said means to curve the tie wire including an element constantly contacting 50 the wire, to curve same to convex inwardly when cut from the bundle.

185. In a bundle tying machine the combination of a support, a pressure foot above the support, an abutment against which to locate a 55 bundle directly into tying position on the support, means for actuating the pressure foot to clamp the bundle so located, an oscillatory means to wrap a tie wire around the bundle including a wheel which the tie wire encircles to bend it 60 so that it will be convex; a cutter for severing the wire; and means to secure the tie ends together.

186. In a bundle tying machine the combination of a support, a pressure foot above the support, an abutment adjustable longitudinally of 65 the pressure foot for locating the bundle in proper binding and tying position on the support, means for actuating the pressure foot to clamp the located bundle, an oscillatory means to wrap a tie wire around the bundle including a 70 wheel which the tie wire encircles to bend it so that it will be convex; a cutter for severing the wire; and means to secure the tie ends together.
